Specification of Letters Patent.

Patented Feb. 2, 1915.

Application filed October 6, 1908, Serial No. 456,418. Renewed January 22, 1912. Serial No. 672,794.

To all whom it may concern:

Be it known that I, FRANK R. McBERTY, citizen of the United States, residing at New Rochelle, in the county of Westchester and State of New York, have invented a certain new and useful Improvement in Telephone-Exchange Systems, of which the following is a full, clear, concise, and exact description.

10 This invention relates to a telephone exchange system, and its object is in general to provide an improved organization of apparatus and circuits whereby connections between subscribers' lines may be made with 15 rapidity and certainty, by automatic switching mechanism which is comparatively simple and inexpensive, and which does not require complicated controlling circuits nor especial care in manipulation, the telephone 20 transmission circuits and signaling circuits being of standard character, and the line being supplied with current from a central battery, as required by modern operating conditions.

25 Some of the features to be claimed in this application relate to an improved system of control for the automatic switching mechanism including a novel form of controlling or sending apparatus by which a sequence of 30 selecting operations may be brought about with great rapidity and accuracy. Other features to be claimed relate to automatic means for controlling the association of the sending apparatus with the operators' connecting circuits, establishing in the required 35 sequence the various circuits governing the operative relation of the selector mechanism to the sender apparatus and to the connecting-circuits and subscribers' lines, establishing 40 telephonic transmission-circuits of standard character as recognized by the best engineering practice, supervising and controlling connections, and restoring the apparatus and circuits to normal condition after use.

45 Some features of the invention will be applicable to systems of the purely automatic type, in which the selectors are controlled by apparatus at the subscribers' stations; but in the system to which I particularly 50 contemplate applying the invention, it is intended that operators shall be stationed at a central office of the telephone exchange, as in the manual system, to answer calls from subscribers and to control and supervise the 55 establishment of connections, the actual line-

switching operations, however, being performed by mechanical selectors; under the electrical control of automatic sending apparatus which is brought into action by the operator. In this system a number of connecting circuits will be provided for the use of each operator in uniting lines, each such connecting circuit having means for uniting it at one end with a calling line, and terminating at the other end in a mechanical selector switch; means being provided for temporarily associating with each connecting circuit the "sending apparatus" to control, in accordance with this invention, the action of such selector and of the succeeding 65 selectors by and through which the circuit is successively extended from the calling line to the line wanted. When the connection is completed, the sending apparatus will be automatically disconnected from the circuit 70 which has been established, leaving it free for telephone transmission, the sending apparatus being then free to serve another connecting circuit in establishing another connection.

80 In accordance with the present invention, the sending apparatus is governed by a bank or set of numeral keys which may be similar in arrangement to those of an adding machine, and may be set in the combinations 85 required to represent any line number of the system; and automatic controlling mechanism is adapted, under control of any such combination of keys, to cause a series of operations of the selective line-switching mechanism such that the circuit will be extended thereby to the line so designated. In this system, therefore, the subscriber may transmit 90 a call in the usual way and give his order to the operator; and the operator upon 95 learning the number of the line wanted will simply depress a combination of keys representing this number, and this will result in the immediate selection of such wanted line.

100 The sending apparatus includes a device which may be termed a point-finder, adapted to traverse a series of points which may be selected by the keys. Means are provided for setting the point finder in operation by the depression of a key, under control of a 105 stopping device which will be actuated when the point selected by such key has been reached. The extent of travel of the point-finder in reaching the selected point measures the selecting operation of a distant me- 110

chanical switch or selector, a movable element whereof is advanced in unison with the point-finder by means of pulsations of current, each pulsation causing or corresponding to a unit of advance of both the selector and point-finder. When the stopping device is actuated by the point-finder in its predetermined limit of travel, the selecting operation is brought to an end, as by 5 10 an automatic switch opening the controlling circuit which has been established between the selector and point-finder. As each point-finding operation is completed, automatic switching mechanism is brought into action 15 to prepare the circuits for another selection; and one selector after another in the train through which the circuit is extended is controlled by such a point-finding operation at the sender until the desired line is 20 reached. Thereupon the point-finder in its final action causes the operation of an automatic switch which disconnects the sending apparatus from the circuit which has been set up, leaving such circuit free for telephone transmission. The successive sending 25 or controlling operations are caused to occur in a definite order, as required, by means of an automatic sequence-switching mechanism associated with the sending apparatus. The 30 selectors are also provided with local controlling apparatus for governing certain independent operations such as those of hunting idle trunks, and the sending apparatus is arranged to suspend its action while such 35 independent operations are taking place at the selectors.

The invention includes various details of circuits and apparatus by which the operations above outlined, and other incidental 40 operations, are brought about. In developing a system of the type described, I have made a series of inventions relating to different parts of the complete organization, which inventions are more or less intimately 45 related to one another, but are none the less distinct in themselves, and are available for use quite independently in other systems. I prefer, however, to illustrate and describe this invention in its application to the complete system for which it was particularly 50 worked out, containing many features which are the subject of other applications hereafter recited. In describing this system it will be necessary in the interest of clearness 55 to set forth specifically and in detail the characteristics and mode of operation of the particular apparatus and circuits shown; but it will be understood that I do not intend such specific descriptive language to be 60 taken as a precise definition of the limits of this invention; the parts, improvements or combinations which are intended to be covered herein being set forth in more general language in the claims. At almost every 65 point in the system minor modifications may

be made in the apparatus and circuits employed, to effect the same results by equivalent electrical or mechanical means, without departing from the essential principles herein disclosed. For the purpose of illustration the system has been shown in the drawings as designed for a small exchange 70 of one thousand lines' capacity, but it will in fact be particularly adapted for use in large cities where each exchange may comprise, 75 for example, ten thousand lines, a large number of such exchanges being connected by inter-office trunk lines. The system may be expanded to provide for automatically connecting any line of such a large exchange 80 with any line of another exchange, through a train of suitable selectors and trunk lines.

In the drawings, Figures 1, 2, 3 and 4 when placed together, edge to edge, in the order named, (Figs. 2, 3 and 4 being placed side by side, and Fig. 1 placed above Fig. 2) 85 form a complete diagram, the lines which continue to the edge of each sheet being continued on neighboring sheets; the whole 90 illustrating the circuits and apparatus involved in extending a connection from a calling line to a line called for. Fig. 1 represents a bank of keys arranged in three 95 sets, representing "hundreds," "tens" and "units" digits, respectively. Fig. 2 represents one form of controlling or sending apparatus adapted to govern the various 100 selecting operations, under control of the key shown in Fig. 1. Fig. 3 represents the calling subscriber's line and the operator's connecting circuit, together with the first 105 selector forming the terminal of such connecting circuit, this being, in the small exchange illustrated, a "hundreds" selector; Fig. 4 represents the final selector to which 110 the circuit may be extended by the first selector, and also represents the called line to which the final selector may make direct connection; Fig. 5 is a front view of one of 115 the sequence-switches which are employed in association with the selectors, and also in association with the sending apparatus, to establish in sequence the operating circuits for the various parts; Fig. 6 is a side view of the sequence-switch; Fig. 7 is a detail 120 sectional view on line 7—7 of Fig. 6; Fig. 8 is a sectional plan view on line 8—8 of Fig. 6.

The same reference-figures indicate corresponding parts wherever shown.

General plan of system.—When any one of the operator's connecting circuits is put into service to answer a call, the sending apparatus is automatically appropriated to the use of that connecting circuit; and a 125 controlling or "stepping" circuit is established between a controlling relay at the first selector and a magnet at the sender which is adapted to operate a step-by-step mechanism. Means are provided for trans- 130

mitting electrical impulses over this stepping circuit, and for operating the selector and the stepping mechanism at the sender in unison therewith. The advance of the stepping mechanism at the sender in unison with the impulses transmitted over the stepping circuit furnishes a means for measuring off at the sender the exact extent of operation of the distant selector; and when a predetermined number of impulses have been transmitted, as indicated by the advance of the sender stepping mechanism to a predetermined point, the stepping circuit may be automatically opened, bringing that particular selecting operation to an end, after which another selection may be made in the same way. Each selector in the train through which the circuit is successively extended will, as it is reached, be brought under control of the sending apparatus by the establishment of the selecting circuit, which includes a controlling relay or magnet at the selector and a relay or magnet at the sender adapted to operate the stepping mechanism thereof.

The extent of advance of the sender stepping mechanism is determined by the selection of one of a series of terminals or "points" over which a "point-finder" is advanced by the stepping mechanism, the particular points required for determining the successive selecting operations being chosen by keys which are depressed by the operator. In the particular system shown, designed for a thousand-line exchange, there are three rows of ten keys each, numbered from 0 to 9 inclusive, one row representing "hundreds," another "tens" and the third "units" digits; and in this system there are three selecting operations, controlled respectively by the keys representing the three digits of the number of the line to be selected. The point-finder apparatus comprises a finder brush arranged to be advanced over a series of terminals by the stepping mechanism or escapement operated by the stepping magnet which responds in unison with the stepping impulses; and the terminals are in three divisions, those in the first division being connected to contacts of corresponding hundreds keys, those in the second division to contacts of corresponding tens keys and those in the third division to contacts of corresponding units keys. Each key is adapted when depressed to select a corresponding terminal—in the present case by connecting such terminal to ground—and the finder brush upon reaching the terminal so selected will complete a circuit for a stop relay. This relay in its response breaks the circuit over which the stepping impulses are transmitted, so bringing the selecting operation to an end. The response of the stop relay also brings switching mechanism

into action to prepare the sender for the next selection, and so on until the last selection has been made, whereupon the stop relay in its response causes switching mechanism to be actuated which will disconnect the sending apparatus from the circuit which has been established, leaving the calling line united through the operator's connecting circuit and the train of selectors to the line which has been selected. In the system shown, the impulses for measuring each selection are derived from a battery associated with the selector under control, and are produced by the action of interrupter-contacts closed periodically in the advance of such selector, which intermittently short-circuit the line. Power is applied to the movable element of the selector under control of a line relay, which is in a portion of the stepping circuit not shunted by the interrupter, and which is released when the circuit is opened by the stop relay at the sender.

The local controlling-circuits at each selector and at the sending apparatus, which must be established in definite order at successive stages of the operation to bring into service different devices or parts as required, are in the present system established by automatic switching appliances which I term sequence-switches. There is a sequence-switch for each selector, and one for the sending apparatus. The sequence-switch consists in its elements of a movable switch-operating member, a number of circuit-changers or switches actuated in sequence as said member is moved from one position to another, an electromagnet, and motor mechanism operated or controlled by said magnet for advancing said movable member. The sequence-switch may control any desired sequence of operations, whether of the same or of different devices. In each position to which its movable member is advanced a circuit is established whereby a given operation of the device under control is made possible, and at the same time another circuit is established, whereby the motor magnet of the sequence-switch may be actuated automatically when such operation of the device under control has been completed; so that as each operation takes place, the sequence-switch will be automatically advanced to the next position, in which a new operation or another stage of the same operation will be brought about, and so on. Finally, the sequence-switch establishes a condition whereby the apparatus under control is returned to its normal condition, and also establishes a circuit whereby the sequence-switch itself will be returned to normal.

Mechanism of selectors.—The mechanism of the selectors shown diagrammatically in Figs. 4 and 5 may be, for example, substan-

4

tially as shown and described in my previous application, Serial No. 418,123, filed February 27, 1908; but an understanding of their general features of construction and mode of operation may be had by reference to the diagrams herein. Each selector has a rotary shaft 50, carrying a frame 60 at the outer end of which a number of contact brushes 51, 52, 53, are pivoted in position to travel over contact terminals 61, 62, 63, mounted in rows concentric with the shaft. Spring tongues 54, 55, 56, extending from insulated metal plates 41, 42, 43, respectively, press against projecting arms of the brushes, and besides making electrical connection therewith, tend to rock the brushes on their pivots in a direction to throw their forward or contact ends outwardly. The brushes are arranged in sets of three. Corresponding brushes in each set are electrically connected in multiple by means of metal plates 41, 42, 43, from which extend the spring tongues 54, 55, 56, and each set is normally latched against the thrust of the spring tongues 54, 55, 56, by a catch 57 which is normally held in the path of movement of the rear ends of said brushes. As shown, the catches 57 are insulating bars mounted on spring latch-arms 58, which are the free ends or tongues of a spring metal plate 59 fixed to the rotary frame 60. In order to bring any set of brushes into position to engage the contacts over which they travel, they must be released by tripping the corresponding catch 57 to allow the brushes to be rocked upon their pivots by their springs 54, 55, 56. This tripping of the brushes is accomplished by a trip-bar 64 which is pivotally mounted on an axis 65 and has at its edge a series of projecting lugs 66 in position to be moved into the paths of the respective latch-arms 58 when the trip-bar is rocked on its axis.

It is intended that only one of the several sets of brushes shall be selected and tripped in a given operation, and the trip-bar is therefore inclined at an angle so that the tripping lugs will face positions successively reached in the rotation of the brush-carrier frame. The trip-bar will be actuated to thrust forward its tripping lugs only for a moment when the end of the latch-arm controlling the desired set of brushes reaches an angular position just in advance of that occupied by the particular lug which is at the proper height to engage that arm. The movement of the trip-bar may be accomplished by a tripping-magnet 67, the movable armature 68 whereof is mechanically connected to said bar.

A segmental metallic plate 70 is mounted in position to be engaged by the contact ends of the brushes as they are tripped, this plate 65 extending to the end of the "trip range"—

that is, through the arc traversed by the brushes as one set after another throughout the series is brought into position to be tripped. At the end of the trip range the bank of line terminals 61, 62, 63, begins. 70 These terminals are arranged in sets of three, corresponding in relative positions to the relative positions of the brushes by which they are to be traversed, and the different sets are arranged in an arc in position to be successively reached in a point-to-point rotary advance of the brushes. 75

To restore the brushes to their latched position when the selector returns to normal, an insulating bar 95 is arranged to be passed over by the brushes in their return journey, the brushes in passing over this bar being raised thereby against the tension of their springs, until their beveled rear ends slip over the catches 57. 80

The motor mechanism for rotating the brush carrier frame may be as follows: An iron plate 73 is mounted to rotate with the shaft 50, but in such manner that it may be given a flat-wise or tilting movement into engagement with one or the other of two iron friction-driving rollers 74, 75, which are located on either side of its axis, said rollers being mounted upon a constantly-driven power-shaft 76. An electromagnet 77, which I term the clutch magnet or power-magnet, is arranged to magnetize the driving rollers 74 and 75 to cause them to attract the iron plate 73. Said plate is provided with cam surfaces, so that in the normal position of the apparatus the surface on one side of the axis 50 will be closer to the driving wheel 75 than the surface on the other side of said axis is to the driving wheel 74. Normally, therefore, when the power-magnet is excited the plate 73 will be drawn into engagement with roller 75 to receive motion therefrom, and the carrier shaft 50 will be rotated in a direction to advance the brushes. 100 After the brushes have been advanced the distance required, the power-magnet will be deenergized, the plate 73 will be released from its engagement with driving roller 75, and said plate will recover from its tilted position by the action of a spring washer 78. 110 The cam surface of the plate being now angularly displaced from the axis of the driving rollers, the body portion of the plate will be nearer to the "return" roller 74 which is of larger diameter than the roller 75, so that when the power-magnet is again energized the plate will be engaged by roller 74, and the shaft 50 will be rotated thereby in a direction to return the rotary carrier to normal position. 120

A cam 80 is carried by the rotary element of the selector to operate a switch. On the first rotary movement, and while the brushes are passing the trip range, the cam forces said spring 81 against an anvil 82, and at 130

the end of the trip range the cam allows the spring 81 to recede from contact 82 and engage the alternate anvil 83.

A make-and-break contact device or interrupter is also arranged to be operated as the brush-carrier of the selector rotates. As shown, an interrupter arm 84 is pivoted in the carrier-frame similarly to the brushes 51, 52, 53, and carries at its forward end a roller 85 which is adapted to travel over a toothed segment 88, thereby causing the arm to vibrate. As the roller rides up on each tooth it rocks the arm 84 in a direction to close a contact 86, 87, and this contact remains closed until the roller has passed over the tooth and has nearly reached the bottom of the following notch. A spring tongue 91, which is mounted upon but insulated from the frame 60, presses against and makes continuous electrical connection with the contact arm 86. A pivoted arm 93, the foot of which rides upon the smooth rim of the toothed segment 88, has a rearward extension which engages an insulating stud carried by the arm 86, to hold said arm against the tension of the tongue 91. By this construction the relative positions of the contacts 86, and 87 in any position of the brush carrier frame depend solely upon the relative distance of the roller 85 from the rim of the toothed segment upon the edge of which it rides, and are independent of slight variations in the radial distance between said toothed segment and the axis of rotation of the brush-carrier frame. The making and breaking of contact 86, 87, as the brush-carrier frame rotates, is thus accurately regulated according to the cutting of the notches in the segment 88. A spring tongue 92, mounted upon but insulated from the brush-carrier frame, and also insulated from tongue 91, bears upon the arm 93, and serves to make electrical connection to the contact point 87, through said arm 93, the rim of the metallic segment 88 upon which it rides, roller 85, riding upon the edge of said segment, and arm 84 carrying said contact point. The terminal wires of the circuit to be interrupted by said contact 86, 87, are therefore soldered or otherwise connected to the tongues 91 and 92 respectively.

The brushes 51, 52, 53, are electrically connected in multiple sets by the terminal plates 41, 42, 43, the plate 41 having tongues 54 making contact with all the brushes 51, the plate 42 having tongues making contact with all the brushes 52, and plate 43 having tongues 56 making contact with all the brushes 53. The two line wires and the test wire of the circuit leading to the selector may be soldered or otherwise permanently connected to the plates 41, 42 and 43, respectively, and these three circuit wires may thus be electrically connected to any set of three stationary terminals 61,

62, 63, in any horizontal level by first tripping the multiple set of brushes which travels over the required level, and then causing the brush-carrier to rotate until the selected brushes reach the desired set of terminals in that level. 70

In the particular system shown in the drawing, each final selector is intended thus to select any one of a hundred sets of terminals, there being three terminals in each set, for the two line conductors and the test conductor, respectively, of a telephone circuit. Each selector will therefore be considered to have thirty brushes, ten sets of three each, and three hundred stationary terminals arranged in ten levels corresponding to the ten sets of brushes, with ten vertical rows of thirty terminals each in all. For simplicity in the diagram, there are shown only two sets of brushes and a few 85 of the contact terminals in the two corresponding levels.

The first selectors may each have stationary terminals arranged in ten levels of three horizontal rows each, corresponding 90 to the sets of brushes; each set of terminals representing a trunk line leading to a final selector. The final selectors will be divided into ten groups, all the final selectors in a given group having direct access to the same one hundred subscribers' lines. All the trunk line terminals in a given level upon each first selector will represent final selectors of the same group; and there may be as many final selectors in each group (and accordingly as many terminals in each level upon the first selectors, as traffic conditions may require). The first selector, by tripping one of its ten sets of brushes, chooses a group of final selectors 105 for reaching subscribers' lines of the desired "hundred," and then, by advancing said brushes over the terminals in the corresponding level may test in rotation the trunk lines leading to such final selectors, and 110 seize the first one which is idle.

Mechanism of sending apparatus.—By reference to Fig. 1, it will be seen that the numeral keys are arranged in three rows of ten keys each, the keys in each row being 115 numbered from 0 to 9 inclusive. The keys are intended to lock in their depressed positions, and in the form shown, the lower end of the plunger 101 of each key carries an iron plate 103 which is adapted to serve 120 as an armature for an electromagnet 102, the pole pieces whereof extend along under the whole row of keys. The magnet 102 is not strong enough to draw down the plunger of a key from its normal position; but if 125 when the magnet is excited any of the keys is depressed, the plate 103 carried by the plunger of such key will stick fast to the pole pieces of the magnet, so that the key will be held in its depressed position until 130

the magnet is deenergized. Springs (not shown) may be provided as usual for returning the keys to normal position when released. Each key when depressed is adapted to close two contacts, one controlling the application of a ground connection to a conductor individual to such key, leading to a corresponding terminal at the point finder apparatus (Fig. 2) and the other contact being adapted to close a circuit common to all the keys of the row.

Referring now to Fig. 2, the operation of the stepping mechanism and the point-finder operated thereby will be readily understood. The finder brush 201 is mounted upon an arm extending radially from the central shaft 202, and is adapted as said shaft is rotated to travel over stationary contact terminals 203 which are arranged in the circular path of travel of said finder brush. In the form of apparatus shown, the point finder shaft 202 is adapted to be rotated by a spring-actuated driving-gear under control of an escapement, the escapement lever 204 being arranged to be vibrated by an electromagnet 205 as said magnet responds to the intermittent electrical impulses. The shaft 202 carries a gear wheel 206, which is arranged to be driven by a gear wheel 207, which is kept under tension by a coiled spring 208. One end of the spring 208 is fastened to the gear wheel 207, and the other end of said spring is fixed to the plate 209, which is rotated from time to time in a direction to wind up the spring. The plate 209 is carried by a shaft 210, which also carries one member of a friction clutch adapted to couple said shaft 210 to a constantly driven power-shaft 211. The gear wheel 207 rotates upon, but independent of, the shaft 210.

The power-shaft 211 carries an iron driving roller 213, and the shaft 210 carries an iron plate 212 which is fixed thereto in such a manner that said plate may be moved flatwise into frictional engagement with said driving roller 213 by the action of an electromagnet 214 which is arranged to magnetize said driving roller. At the end of each complete revolution of the point finder shaft 202, the electromagnet 214 is energized to draw the members 212, 213, of the friction driving gear into engagement, and thereby cause the shaft 210 to be rotated in a direction to wind up the spring 208. A contact 215 is arranged to be closed by a cam-lever 216 the end of which rides upon the periphery of said plate, said lever being moved outwardly when the plate 212 leaves its normal resting position. This contact 215 controls a local circuit for the electromagnet 214, whereby said magnet may be maintained energized until the plate 212 has made a complete revolution, whereupon the

contact 215 will be opened and the magnet 214 deprived of current.

The gear wheel 206 mounted upon the shaft 202 of the point finder engages a pinion 217 mounted upon the shaft of an escapement wheel 238. The escapement lever 204 is mounted upon the armature of the electromagnet 205, and as said armature is vibrated it permits the escapement wheel 238 to rotate step by step, thereby rotating the shaft 202 of the point finder, and advancing the finder brush 201 over the series of stationary terminals 203.

The stepping impulses, which are received from a distant point and may be comparatively feeble, need not be required to act directly upon the stepping magnet to perform the mechanical work of operating the escapement. Preferably a sensitive relay 218 is connected in the selecting circuit to receive and respond to the selecting impulses, and the stepping magnet 205 which directly operates the escapement is connected in a local circuit controlled at the front contact of said stepping relay.

The stationary terminals 203 of the point finder apparatus are arranged in three divisions, the terminals in the first division being connected respectively to contacts of corresponding hundreds keys; the terminals in the second division being connected to contacts of corresponding tens keys, and the terminals in the third division being connected to contacts of corresponding units keys. In the apparatus shown there are at the end of each division two idle terminals, in addition to the ten terminals connected to the keys; and there is also at the beginning of each division an extra terminal, s^1 , s^2 or s^3 , as the case may be. In the normal starting position s^1 of the finder brush 201, and in the second and third starting positions s^2 and s^3 thereof the finder brush lies one step back of the first or zero terminal of the corresponding division.

The continuity of the stepping circuit shown in heavy lines is controlled at the back contact of a stop relay 219, which is connected between the free pole of a grounded battery 220 and the finder brush 201. When the finder brush in its advance over the terminals 203 reaches the one which has been grounded by the corresponding key, the stop relay 219 is energized and opens the selector circuit including the stepping relay 218, whereby the selecting operation is determined. The stop relay in its response is also arranged to close a circuit for the motor magnet of the sequence-switch associated with the sender, to advance said sequence-switch to another position in which another selecting operation may be brought about. The stop relay 219 is also adapted in its response to close a local circuit for

the stepping magnet 205, including an interrupter 221, whereby the point finder may be independently advanced from the point at which it found the terminal 5 grounded by the corresponding key, to the starting point s^2 or s^3 , as the case may be, at the beginning of the next division of terminals; and after the last selecting operation the local circuit from the interrupter 221 is 10 completed until the brush finder has traveled clear around to its original starting point s^1 . A cam 222 carried by the point finder shaft 202 is adapted to close contacts 223 and 224 in all positions except when the 15 finder brush is resting upon one of the starting points s^1 , s^2 or s^3 . These contacts 223 and 224 control the local circuit for the stepping magnet 205, through the interrupter 221, and by opening when the finder 20 brush reaches a starting point s^1 , s^2 or s^3 , as the case may be, cause the finder brush to be arrested in such starting position.

Mechanism of sequence-switches.—In the form of sequence-switch mechanism shown in Figs. 5 to 8 the movable member is a vertical rotary shaft 7 carrying a number of switch-operating cams 8, said shaft being arranged to be driven by power applied through the agency of an electromagnetic clutch. The constantly driven power-shaft 11 carries a friction driving disk 10 which is adapted to be drawn into engagement with a friction roller 9 carried upon the shaft 7, by the action of a clutch magnet 12. 25 The roller 9 and the disk 10 are of iron, and the motor magnet 12 is adapted when excited to magnetize said roller 9, which serves as a rotary pole piece for said magnet; whereby the driving disk 10 is attracted into 30 engagement with said roller, the rotation of the shaft 7 thus continuing as long as the motor magnet 12 remains excited.

The cams 8 carried by the rotary shaft 7 are arranged to operate switch springs 13, 45 forcing said springs into engagement with outer contacts 15, or allowing them to engage their alternate inner contacts 14, according to the positions of said cams. As many cams and switches may be provided 50 as the particular apparatus to be controlled may require. Certain of the switch contacts operated in the successive positions of the movable switch element may control circuits for the motor magnet 12. A special switch, 55 such as shown in Fig. 8, is also preferably provided to control a local circuit for said motor magnet, whereby after the initial energizing circuit is broken by one of the other switches, the motor magnet may still 60 be excited by current in the local circuit until the next intended stopping position of the rotary element is fully reached. As shown in Fig. 6, the cam 16 for operating the "local" switch is adapted to be engaged 65 by a cam roller 17 carried by a pivoted

switch lever 18. A spring 19 is arranged to act upon said pivoted lever 18 so as to press the cam roller 17 against the edge of the cam 16. When the roller 17 rides upon a tooth or high part of the cam 16, said lever 18 closes a contact 20 which controls the local circuit for the motor magnet. The teeth of the cam 16 have inclined edges, so that the cam roller 17, after riding over the point of a tooth, is forced down the opposite slope by the action of the spring 19, and thus tends to push against the cam to continue the rotation thereof until the roller 17 reaches the bottom of the following notch. The rotary element is thus brought to rest accurately in the position where it is intended to stop. In the operation of the device the circuit will first be closed for the motor magnet through one of the springs 13, and one or the other of the contact anvils 14 or 15 of such spring. Then as the motor magnet is excited and the shaft of the sequence-switch begins to rotate, the contact through which the motor magnet was initially excited may be broken, but the local circuit will be maintained for the motor magnet through the contact 20 closed by the cam 16, and the rotary element will thus continue to advance until the cam roller 17 reaches the bottom of the next notch of the cam 16.

In the diagram, Figs. 1 to 4 inclusive, the switch-springs of the sequence-switches are not shown in their actual arrangement, but are so located as to give the clearest arrangement of circuits; and the operating cams are not shown. The positions of the rotary element of each sequence-switch in which any of its contacts are closed are indicated by numbers placed adjacent to such contacts; each contact being open in all positions except those indicated by the adjacent numbers. For example, contact 409 is closed in the 1st or normal position of the sequence-switch, and in the 2nd and 13th 100 positions thereof, as indicated by the numbers 1—2—13 placed adjacent to that contact, and is opened in all other positions. But each sequence-switch has a special contact governing the local or locking circuit 105 of its motor magnet, such as contact 20 operated by cam 16 in Fig. 8. As these special contacts are closed only while the rotary element is in transit from one stopping position to the next, the numbers are placed 110 on the side of the switch lever opposite from the contact, and do not indicate positions in which the contact is closed, but indicate instead positions in which it is open. Thus, 115 by reference to the numbers appearing adjacent to the contact 20^b of the sequence-switch of the first selector (Fig. 3) it is seen that this contact is closed between the 1st position and the 3rd, open in the 3rd, closed between the 3rd and the 4th, open 120

in the 4th, closed between the 4th and 5th, and so on; and that between the 1st and 3rd positions and between the 8th and 13th positions, the contact is continuously closed. 5 The movable element of this sequence-switch, therefore, after leaving the 1st position, will run through to the 3rd without a stop; and upon leaving the 8th position will likewise run through to the 13th position without a stop:

10 *Operation of system.*—A further detailed description of the apparatus used in the system, and a statement of the electrical connections of each part will be unnecessary, as devices of known types are indicated by the usual conventional symbols, and the electrical connections are clearly shown in the diagram. Certain of the usual appliances required in an actual telephone 15 system, such, for example, as the operator's telephone set, are not shown, because their connections and manner of use will be well understood by those skilled in the art, and to show them in detail would unnecessarily complicate the diagram. Several batteries 20 are shown in the diagram, and for convenience in tracing the circuits these are designated by different numerals, but it will be understood that in practice a single central battery common to the exchange may be employed, connected as indicated.

25 The organization and mode of operation of the system can best be understood by tracing the operations or steps involved in extending the connection of a calling line to a line called for, transmitting the necessary signals, making the requisite tests, establishing the talking circuit, and finally disconnecting the lines and restoring the apparatus and circuits to normal condition.

30 Let it be assumed that subscriber at station No. 401 (Fig. 3) desires to converse with the subscriber at station No. 950 (Fig. 4). The calling subscriber signals the central office in the usual way by taking his telephone receiver from its switch hook, thereby closing the line circuit and causing the line relay at the central office to close a local circuit for the line signal lamp 402. 35 The operator responds to the call by inserting her answering plug 403 in the spring-jack of the calling line and depressing her listening key to bring her telephone set (not shown) into circuit in order that she may learn the number of the subscriber wanted.

40 The insertion of the answering plug completes the circuit for the cord relay 405, and the subsequent operation of the listening key closes a special contact 404 thereof, which completes a circuit from battery 408, through the motor magnet 407 of the sequence-switch associated with the first selector, normally closed contact 409 of said sequence-switch, contact 404 of the listening key, front contact of the cord relay 405, to

50 earth. The sequence-switch therefore begins to advance, and by reference to the numerals near the local switch lever 20, it will be seen that the local circuit for the motor magnet 407 remains closed from the first position to the third, so that said sequence-switch advances to its third position without stopping. At the second position a contact 411 is closed, controlling a common branch from the supervisory signal lamps 412 and 413, to earth, whereby said supervisory signal lamps are brought into service under the control of their respective supervisory relays 414 and 415. As the sequence-switch of the first selector reaches the third position, it closes a contact 416 by which a ground connection is applied to the sender lead 418, and a circuit is thereby completed for relay 300 (Fig. 2) which controls the seizure of the sending apparatus by the connecting circuit which has been put into use. This circuit is traced from battery 301 through the sender-controlling relay 300, to conductor 418, which is multipled to the contacts 416 of the sequence-switches of all the connecting circuits of an operator's position, the circuit being completed through the contact 416 of the one which has been taken for use, to earth. In the same position (3) of the sequence-switch a contact 417 is closed whereby the motor magnet 407 thereof is connected to the sender lead 419, which is adapted to be connected to earth by contact 303 of the sequence-switch associated with the sending 55 apparatus.

60 The circuit 418 controlled at contact 416 furnishes a means by which the sequence-switch of the sending apparatus can be caused to advance to put the sending apparatus into condition for use, when any of the connecting circuits is put into service; and the circuit 419 controlled at contact 303 of the sequence-switch associated with the sending apparatus furnishes a means whereby the sending apparatus may exercise a reciprocal control over the sequence-switch of the first selector. The circuit 419 will be closed, as will hereafter appear, when the sender sequence-switch advances to its third position in response to the depression of one of the hundreds keys. When the relay 300 is excited it closes a circuit from ground through the front contact of said relay, contact 304 of the sender sequence-switch, through the motor magnet 317 of said sequence-switch, to the free pole of a grounded battery 316. The sender sequence-switch therefore moves immediately to its second position.

65 The operator having now communicated with the calling subscriber, and having learned the number of the line wanted, depresses keys (Fig. 1) representing the digits of such number. In the case assumed,

where line No. 950 is called, the operator depresses the hundreds key No. 9, the tens key No. 5, and the units key No. 0. These keys, when depressed, will ground corresponding points in the first, second and third divisions, respectively, of the stationary terminals in the point-finder apparatus. As soon as one of the hundreds keys has been depressed, a circuit is completed for the motor magnet 317 of the sender sequence-switch, through contact 306 thereof, and through the contact 107 of the particular hundreds key which has been depressed (in this case the 10th key No. 9) to earth; whereby the sender sequence-switch is advanced from its second to its third position. In this position the contact 303 is closed, completing the circuit 419 for the motor magnet of the sequence-switch associated with the first selector of the connecting circuit which has been put into use, whereby said last-mentioned sequence-switch is moved from its third to its fourth position. The sequence-switch of the sender in its 3rd position also closes a contact 308 which brings the motor magnet 317 thereof under control of a front contact of the stop relay 219, so that when said stop relay shall be excited at the end of the first selecting operation the sender sequence-switch will be advanced from its 3rd to its 4th position. As soon as the sequence-switch associated with the first selector moves to its 4th position, a circuit is established by which the controlling line relay of the first selector is energized in series with the stepping relay at the sender. This circuit is as follows: from the free pole of grounded battery 421 at the first selector, through the line relay 420, contacts 422 and 423 of the sequence-switch, to sender lead 424, thence through the stepping relay 218 of the sender, (Fig. 2) back contact 230 of the stop relay 219, through contact 309 of the sender sequence-switch, to earth.

The relay 420 at the selector, in closing its front contact, completes a circuit from ground, through contact 426 of the sequence-switch and power magnet 77, to the free pole of grounded battery 425. The power magnet, being thus excited, attracts the tilting disk 73 into engagement with the driving wheel 75, and the brush-carrying frame of the selector is started to rotate, this rotation being continued as long as the line relay 420 remains excited.

The stepping relay 218 at the sender is excited by current in the circuit 424 previously traced, as soon as the sequence-switch at the first selector closes contacts 422 and 423. This stepping relay 218 closes at its front contact a local circuit from ground, through back contact of armature 229 of the stop relay 219, to the stepping magnet 205, and free pole of grounded battery 225. The

armature of the stepping magnet 205 in its attractive movement, allows the escapement wheel 238 to take a half step, moving the finder-brush 201 from its normal position 3¹ to an intermediate insulating segment 4¹ between said position 3¹ and the first or zero terminal in the division assigned to the hundreds keys. As the brush-carrier frame of the selector is now rotated, the interrupter arm 84 is vibrated by the roller 85 riding over the teeth of segment 88. As said roller rides up on each tooth, the cam 84 is moved in a direction to bring the contact point 87 against the anvil 86. This completes a short circuit from contact 422, through wire 427, back contact 428 of the trip magnet 87, spring 91, contact anvil 86, contact point 87, arm 84, roller 85, segment 88, arm 98, spring 192, to earth at 429; thereby diverting current from the stepping relay 218 at the sender and causing said relay to release its armature. When the armature of the stepping relay is retracted it opens the local circuit of the stepping magnet 205, which allows its armature in turn to be retracted, and so permits the escapement wheel 238 to take another half step, moving the finder brush 201 to the first or zero terminal in its path.

As the selector finishes a complete step, and the interrupter roller 85 reaches the bottom of the next notch, the contact 86, 87, is opened, breaking the short circuit 427, and permitting the flow of current again to the stepping relay 218, unless the stop relay 219 has in the meantime opened the stepping circuit at the sender. As successive impulses are delivered to the stepping relay 218, the selector and the point-finder at the sender are thus advanced in unison from step to step, until the finder brush 201 finally reaches the terminal which has been grounded by the depressed hundreds key. When this grounded terminal is reached, a circuit is completed from the free pole of grounded battery 220, (Fig. 2) through the stop relay 219, to the finder brush 201 and the terminal with which it is in contact, and thence to ground at the contact 104 (Fig. 1) of the key which has been depressed. The stop relay 219 when thus excited opens its back contact 230, thereby breaking the selecting circuit 424 which includes the stepping relay 218 at the sender and the line relay 420 at the selector, the result of which will be to cause one of the ten sets of brushes to be tripped at the selector, as will hereafter be explained. The particular set of brushes which is tripped depends upon the number of steps the selector takes in unison with the point-finder, before said point-finder reaches the terminal grounded by the depressed hundreds key as above described. The stop relay when excited also closes a contact 226 to complete a locking circuit for its own

- magnet through contact 310 of the sender sequence-switch; closes a contact 228 to complete a circuit through contact 308 for the motor magnet 317 of said sequence-switch, whereby the latter is advanced to the fourth position; and closes a contact 232 which completes a circuit for the stepping magnet 205 through contact 223 (operated by the cam 222 on the point-finder shaft) and interrupter 221 to earth. When the local circuit of stepping magnet 205 is thus completed through the interrupter 221, the escapement is again operated and the finder brush 201 thereby caused to continue its travel, passing from the terminal which was grounded by the depressed hundreds key to the next starting position s^2 immediately in advance of the next or tens division of terminals in the path of said brush.
- 20 In the starting position s^2 (and also in the starting position s^3 preliminary to the third or units division of terminals) the finder brush 201 rests upon a contact piece which is connected directly to battery.
- 25 When the finder brush 201 reaches the second starting position, therefore, the stop relay 219, which is connected between the battery and the finder brush, is short-circuited. When thus released, the stop relay 219 opens contact 228 controlling the local interrupter circuit for the step magnet, opens contact 226 controlling its own locking circuit; closes contact 231 to complete a circuit through contact 312 of the sequence-switch, whereby the latter is moved to its fifth position; and closes contact 230 to reestablish the selecting circuit which includes the stepping relay 218 at the sender and the line relay of the distant selector.
- 40 A number of dead terminals are provided in the path of the finder-brush 201 between the last terminal of the division connected to the hundreds keys and the starting position s^2 preliminary to the next division of terminals, connected to the tens keys; and likewise a number of dead terminals are provided between the last terminal of the tens division and the starting position s^3 preliminary to the units division. The space occupied by these dead terminals is provided for the purpose of securing a time interval during which the stop relay 219 shall remain excited to hold the stepping circuit open after the first and second selections, before the finder brush reaches the preliminary or starting position for the next selection and short-circuits said stop relay. This time interval during which the selecting circuit is held open at the sender allows the line relay at the selector to remain de-energized long enough to permit the brush carrier to travel through a distance sufficient to trip a set of brushes before said line relay is excited again to short-circuit the trip

magnet, as it will be when the selecting circuit is again closed at the sender.

When the circuit is first established through the line relay 420 at the selector to the sender lead 424, and said line relay by closing at its front contact the local circuit 70 for the power magnet 77 causes the brush-carrier of the selector to begin its journey, the cam 80 upon the shaft of the selector forces contact spring 81 into engagement with its anvil 82. This completes a circuit 75 from ground through contact 432 of the sequence-switch associated with the selector to the motor magnet 407 of said sequence-switch, and the free pole of battery 408; whereby said sequence-switch is moved from 80 its fourth to its fifth position. The contacts 422 and 423 remain closed in this position, and line relay 420 remains continuously excited as long as the circuit 424 is closed through the back contact 230 of the 85 stop relay 219 at the sender.

The short circuit of the line which causes the finder brush at the sender to take the final half-step which brings it to the terminal grounded by the depressed units key, is 90 produced by the contact 86, 87, of the interrupter while the roller 85 is riding up on a tooth of the segment 88. Now, when the line circuit is opened by the stop relay at the sender, which is energized the moment the finder brush contacts with the grounded terminal, the line relay 420 at the selector will be held excited only by current flowing in the circuit controlled by the interrupter contact; and when said contact is 100 opened as the roller 85 rides down from the tooth in question into the following notch, the line relay will be released. The result of this will be to cause the trip magnet 67 to be excited to trip a set of brushes, as will 105 presently be described. The provision for releasing the line relay to cause the excitation of the trip magnet only after the opening of a local interrupter contact operated by the movable element of the selector itself 110 insures the accurate timing of the tripping operation, and thus the accurate selection of the set of brushes to be tripped.

In retracting its armature, the line relay 420 opens the path previously traced from 115 power magnet 77, through contact 426, to earth, which path is a short circuit about the trip magnet 67. When the armature of the line relay leaves its front contact, therefore, the trip magnet will be excited in series 120 with the power magnet by a circuit from battery 425, through said magnets 77 and 67, to contact 430 of the sequence-switch (now closed) and earth.

Now, as the brush-carrier frame of the 125 selector continues to rotate, it will bring one of the latch arms 58 into engagement with a corresponding one of the tripping lugs 60

upon the trip-bar 64, which has been pressed forward by the trip magnet 67. The particular one of the latch arms 58 to be engaged by a tripping lug will depend upon the number of steps through which the selector had advanced before the trip magnet was excited. In the case assumed, where the hundreds key No. 9 was depressed, the selector and the point-finder will have taken ten full steps in unison before the release of the line relay caused the trip magnet to be excited. In those ten steps the latch arms of the first nine sets of brushes (counting from the bottom up) had successively passed the points at which they might have been tripped, leaving the latch arm of the tenth set of brushes in position to be engaged by the projecting lug of the trip bar as the selector continues to advance. The latch arm when engaged by the tripping lug is detained thereby sufficiently to release the three brushes normally held by said latch arm, allowing these brushes to be rocked upon their pivots by their springs 54, 55 and 56; and so thrust into contact with the grounded metal plate 70. The first selection, in which the point-finder of the sending apparatus took ten steps under control of the 10th hundreds key No. 9, has thus resulted in bringing into service the 10th set of brushes of the first or hundreds selector, the other brushes remaining out of service.

The set of brushes so selected may now, by a further rotary movement of the brush-carrier, be caused to travel over the line terminals in the corresponding row or level. In the system under consideration, the line terminals in each level of the first selector represent trunk lines leading to final selectors of the same group. In other words, each set of line terminals in the 10th lever which has been selected represents the conductors of a trunk line leading to a final selector of the 10th group, which has direct access to the terminals of subscribers' lines numbered from 900 to 999. Any of the final selectors of this hundreds group will serve to complete the desired connection; and after a set of brushes has been tripped, as before described, the first selector must therefore advance the selected set of brushes over the corresponding horizontal row of trunk line terminals, until a set is reached representing a final selector which is idle. This "hunting" operation will presently be described.

It will be noted that as soon as the third or test brush of the set which was tripped touches the grounded metal plate 70, the line relay 420 is again excited by current from battery 421, through contacts 422 and 463

of the sequence-switch to the plate 43 and the tongue 56 thereof which bears against the arm of the selected test brush 53, through said brush to the plate 70 and ground. The line relay 420 is thus immediately excited as

soon as a set of brushes has been tripped, and again closes at its front contact the short circuit of the trip magnet 67, said trip magnet having been excited only long enough to trip the set of brushes. 70

The cam 80 is shaped so that when the rotary element of the selector has advanced all the brushes thereof beyond the trip range, the spring 81 will be allowed to engage the contact anvil 83, completing a circuit through contact 433, to the motor magnet of the sequence-switch, which thereupon moves to the 6th position. In leaving the 5th position the contact 423 is broken, disconnecting the line relay 420 from the sender lead 424; 81 but contact 422 remains closed, connecting said line relay through contact 463 to the third or test brushes 53 of the ten sets in multiple. As only one set of brushes has been brought into operative position, the 88 other multiple sets may be disregarded.

The sequence-switch in leaving the 5th positions also opens the contact 430 controlling the circuit for the trip magnet 67, thus opening the branch by which the power 90 magnet was previously excited in series with the trip magnet, and leaving said power magnet dependent for its excitation upon current in the circuit controlled at the front contact of the line relay. Said line relay 95 will now govern the further advance of the selector brush in "hunting" an idle trunk.

The segment 88 of the selector is provided with a long tooth 89 to be engaged by the roller 85 of its interrupter while the brushes 100 are passing between the end of the trip range and the beginning of the range containing the line terminals. As the brushes pass off the end of the grounded metal segment, the interrupter roller is passing over 105 the long tooth 89, and contact 86, 87, is closed, maintaining the line relay 420 excited and the stepping relay 218 short-circuited. As the brushes reach the first set of terminals, however, (in the case of the 110 first selector) and the interrupter contact 86, 87, is opened, breaking the short circuit 427, and leaving the line relay 420 dependent for its excitation upon a circuit which may be completed through the test brush 53 of the 115 set which has been tripped to a test terminal 63 of the set of terminals upon which the brushes may be resting. If the trunk line represented by the three terminals upon which the brushes of the selector are resting 120 is busy, the test terminal 63 thereof will be connected to earth, as will hereafter be explained, but if the trunk line is free, the test terminal 63 thereof will have no such earth connection.

As each set of terminals is reached by the brushes, the circuit for the line relay 420 may therefore be completed through the test brush 53 and test terminal 63 of the trunk line, to earth, if such trunk line is busy; and if 130

such test circuit is completed the line relay will remain excited and maintain the circuit for the power magnet 77 closed; so that the brush carrier will continue to be advanced as long as the brushes are passing over the terminals of lines which are busy. While the test brush is passing from each terminal to the next, the circuit for the line relay is closed by the interrupter contact 86, 87. As the test brush reaches each terminal, the circuit for the line relay 420 through the interrupter contact 86, 87, is broken; and as soon as the test terminal of an idle line is reached, there being no ground connection upon such test terminal, no circuit will exist for the line relay 420, and said relay will be released, breaking the circuit of the power magnet 77, and causing the selector brushes to come to rest upon the terminals of the line so tested and found idle. The line relay 420 in recovering also closes at its back contact a circuit through contact 484 to the motor magnet 407 of the sequence-switch, which is thereby moved from the 6th to the 7th position. In the 7th position the circuits for the test relay and power magnet of the selector are open, and the sender leads 424 and 434 are connected through contacts 436 and 437 to the line brushes 51 and 52, respectively, and so to the conductors 501 and 502 of the trunk line leading to the final selector. Contacts 465 and 464 are also closed, connecting the test brush 53 to earth, and so establishing the grounded or "busy" condition for all the multiple test-terminals of the trunk line selected.

As a result of the first selecting operation under control of the depressed hundreds key, the circuit has thus been extended through the first selector to a trunk line terminating in a final selector which has direct access to all the subscribers' lines of the "hundreds" group corresponding to the numeral of the hundreds key which was depressed. Another selecting operation will now take place under the control of the depressed tens key to cause the chosen final selector to trip the set of brushes which travel over subscribers' lines in the desired tens level; after which a third selecting operation will take place under control of the depressed units key, to cause the tripped set of brushes to advance over the terminals in the corresponding level to the particular set connected to the called subscriber's line.

When the finder brush 201 reaches the second starting position s^2 and the stop relay 219 is short-circuited and released, back contact 230 of said stop relay controlling the stepping circuit is closed, but the stepping circuit will still be open at a contact 311 of the sender sequence-switch. Contact 309 of the sequence-switch, by which the stepping circuit was closed to earth during the first selection, is opened when the sequence-

switch leaves the first position. When the stop relay 219 is released at the time the finder brush reaches the second starting position s^2 , it completes the circuit from ground through its back contact 231 and contact 312 of the sender sequence-switch, through the motor magnet 317 thereof, to the free pole of battery 316. The sequence-switch is thus advanced to the fifth position; and in this position a circuit will be completed for the motor magnet 317, through contact 313 and through contacts 108 and 109 of the tens and units keys respectively, to earth, provided a tens key and a units key has been depressed. Upon the completion of this circuit the sender sequence-switch will be advanced to the 6th position, in which contact 311 controlling the stepping circuit will be closed and the sending apparatus will now be in condition to respond to the next set of stepping impulses which will be transmitted from the final selector, Fig. 4.

As soon as the brushes of the first selector have come to rest upon the terminals of a trunk line leading to an idle final selector, and the contacts 436 and 437 have been closed, the stepping circuit is established as follows: from battery 504 at the final selector, through the line relay 520 thereof, to trunk line conductor 501 leading back to the terminal 61 of said trunk line at the first selector, thence through the brush 51 of said trunk selector, spring 54 resting upon the arm of said brush, plate 41, contact 436, sender lead 424 to stepping relay 218 at the sender, through back contact 230 of the stop relay 219, contact 311 of the sender sequence-switch to the other sender lead 434, thence through contact 437 at the first selector, to plate 42, tongue 55 and brush 52 thereof, to terminal 62 of the trunk line, conductor 502 of said trunk line, through the normally closed contact 505 of the sequence-switch associated with the final selector.

The line relay 520 of the final selector corresponds generally to the relay 420 of the first selector. When excited by current in the circuit just traced it closes at its front contact a circuit from ground through the normally closed contact 508 of the sequence-switch and motor magnet 507 thereof, to the free pole of battery 506. The sequence-switch associated with the final selector is thus moved to its second position, in which contact 526 is closed, whereby the line relay 520, remaining excited, closes a circuit from ground through its front contact and contact 526 of the sequence-switch through the agency of power magnet 77 of the final selector, to the free pole of battery 525. The power magnet being thus excited, the brush carrier is started in rotation, and as the interrupter roller 85 passes over its

toothed segment 88 it makes and breaks the contact 86, 87, establishing at each closure of said contact a short circuit of the line, from line relay 520 to conductor 527, contact 522 of the sequence-switch, back contact 528 of the trip magnet 67 of the final selector, through the interrupter contact 86, 87, to earth. The stepping relay 218 at the sender is deenergized each time such short circuit at the final selector is closed.

As the brush carrier of the final selector begins to rotate, the cam 80 of said final selector forces the spring 81 into engagement with the contact anvil 82, completing a circuit to ground through said contact 82 and contact 522 of the sequence-switch associated with the final selector, to the motor magnet 507 of said sequence-switch and the free pole of grounded battery 506. The sequence-switch is thus moved to the third position, in which a set of brushes may be tripped.

When the selecting circuit is established, connecting the line relay of the final selector and the stepping relay 218 of the sender in series, said stepping relay 218 at each impulse received from the selector completes the local circuit for the step magnet 203, and the escapement of the point finder apparatus is operated as before described, now advancing the finder brush 201 over the terminals in the second or tens division.

When the finder brush 201 in its advance reaches the tens terminal which has been grounded by the depressed tens key, (in this case terminal No. 5) the stop relay 219 is excited, as before, and opens its back contact 230 controlling the stepping circuit. Said stop relay also closes its own local locking circuit at contact 226, closes contact 228 to complete a circuit for the motor magnet of the sender sequence-switch, whereby the latter is moved from the 6th to the 7th position, and closes contact 232 to complete the local circuit for step magnet 203, through the interrupter 221. The finder brush is therefore moved to the third starting position s^3 , the stop relay remaining excited until said position s^3 is reached, whereupon said stop relay is short-circuited as before described. The stop relay in recovering opens its locking circuit at contact 226; opens the interrupter circuit at contact 232; closes contact 231 to complete a circuit for the motor magnet of the sequence-switch, whereby the latter is moved from its seventh to its eighth position; and closes contact 230 to reestablish the selecting circuit 424-434 to await the next set of selecting impulses to be received from the final selector. In the meantime the following operations take place at the final selector:

The line relay 520 is released when the interrupter roller 85 enters the first notch after the finder brush at the sender reaches

the point grounded by the depressed tens key. In retracting its armature said line relay opens the short circuit of the trip magnet 67, leaving a circuit established from battery 525, through power magnet 77, 70 trip magnet 67, contact 530 of the sequence-switch, and back contact 531 of the test relay 550, to earth.

The operation of tripping a set of brushes is the same as previously described with reference to the first selector. The particular set of brushes to be tripped is dependent upon the particular tens key which was depressed. That is to say, in the case assumed, where the tens key No. 5 was depressed, the brush carrier of the final selector will take six steps (corresponding to the six steps of the point finder from position s^2 to the sixth terminal No. 5 in the tens division on the point finder apparatus) before the trip magnet is excited, whereby the sixth set of brushes (counting from the bottom up) will be tripped. The sixth tens terminal in the bank of line terminals on the final selector has thus been chosen. There are ten sets of line terminals in this level, representing the subscribers' lines Nos. 950 to 959 inclusive. The final selection, under control of the units key, will determine the particular set of line terminals upon which the selector brushes will be brought to rest.

When the test brush 53 of the set which is tripped makes contact with the grounded metallic segment 70 of the selector, a circuit is completed from battery 504, through the line relay 520, to contact 538 of the sequence-switch, test brush 53, segment 70 and earth. This maintains the short circuit of the portion of the line leading back to the sender, and also causes the line relay at the selector to be excited, again short-circuiting the trip magnet to prevent the tripping of another set of brushes.

As the brushes leave the segment 70 at the end of the trip range, and enter upon the range of line terminals, the interrupter in passing over the long tooth 89 of the segment 88 maintains a short circuit of the line, through the interrupter contact 86, 87. When all the brushes of the final selector have passed the trip range, the cam 80 allows the contact 83 to be closed, completing a circuit for the motor magnet 507 of the sequence-switch associated with the final selector, whereby said switch is moved from the 3rd to the 4th position. In this position the trip magnet is permanently cut out of circuit by the opening of contact 530.

In the final selector, the segment 88 is provided with an extra notch in advance of the notches corresponding to the positions in which the brushes rest upon the line terminals. As the interrupter roller 85 of the final selector passes down from the long

tooth into this first notch in advance of the notches corresponding to line connecting positions, the short circuit controlled by the interrupter contact 86 is broken, and the 5 first of the new series of selecting impulses is applied to the stepping magnet 218 at the sender.

The back contact 230 of the stop relay 219 at the sender having been closed when the 10 finder brush reached the third starting position s^3 , the selecting circuit is completed at the sender to await the first of the "units" 15 selecting impulses to be received from the final selector. The stepping relay 218 in responding to the first impulse transmitted when the interrupter roller of the final selector enters the first notch following the long tooth 89 of the toothed segment, causes the stepping relay to complete the local circuit 20 for the step magnet 205, whereby the finder brush 201 is advanced a half step. Now as the interrupter roller at the final selector rides up on the next tooth, and short-circuits the stepping relay at the 25 sender, the local-circuit of the stop magnet 205 is opened, and permits the escapement to take another half step, advancing the finder brush 201 to the first or zero terminal 30 in the division of terminals which are connected to the units keys.

As stepping impulses are delivered from the final selector to the stepping relay 218 at the sender, the finder brush 201 may thus be advanced over the row of terminals in 35 the third division until a terminal is reached which has been grounded by the corresponding units key. In the case assumed, where line No. 950 was called, and units key No. 0 was depressed, the first or 0 terminal in the 40 third division will be grounded, and the finder brush 201 after having taken the two half steps from position s^3 to the first or zero terminal, will complete at said terminal a circuit for the stop relay 219 which will 45 operate as before to open the stepping circuit at contact 230.

Now as the interrupter roller 85 at the final selector enters the second notch after the long tooth 89, (that is, the first notch 50 corresponding to a position in which the brushes rest upon line terminals) the short circuit 527 will be broken at the interrupter contact 86, 87. As the stop relay 219 at the sender has already been excited, due to the 55 fact that the first or 0 units key has been depressed, no circuit will exist for the line relay 520 at the final selector when the interrupter contact 86, 87, is broken, and said line relay will be deenergized. The circuit 60 for power magnet 77 will thus be broken when the line relay 520 leaves its front contact, and the brush carrier frame will cease to rotate, the selected set of brushes having been brought to rest upon the first set of line

terminals in the sixth level. These are the 65 terminals of the two line conductors and the test conductor, respectively, of the subscriber's line No. 950, which was called. The selection is thus completed.

When the stop relay 219 is excited as the 70 finder brush 201 reaches the point grounded by the depressed units key, it closes at its front contact 228 a circuit for the motor magnet 317 of the sender sequence-switch, through the contact 308 thereof, whereby 75 said sequence-switch is advanced from the 8th to the 14th position, the contact 20^a controlling the local circuit for the motor magnet of said switch being continuously closed until the 14th position is reached. 80 The stop relay 219 also closes at contact 226 a locking circuit for its own winding, and closes at the front contact of armature 229 the local circuit for the step magnet 205, through the interrupter 221. The finder 85 brush 201 therefore begins its onward journey around to the starting point s^1 .

When the sender sequence-switch reaches the 10th position, the contact 303 is closed, and remains closed in the 10th, 11th and 12th 90 positions. This contact 303 completes a circuit from ground to the sender lead 419, through the contact 417 of the sequence-switch associated with the first selector, and through the motor magnet 407 of said sequence-switch to the free pole of battery 95 408. The last mentioned sequence-switch therefore advances to the 8th position. In this position the sender leads 424 and 434 are cut off from the operator's connecting circuit by the opening of contacts 436 and 437; and contacts 461 and 462 are closed, uniting the main conductors of the connecting circuit from the answering plug 403 to the brushes 51 and 52 of the first selector, and 100 over the circuit which has been established to the final selector, the brushes whereof 105 now rest upon the terminals of the called line.

When the sender sequence-switch leaves 110 its 12th position, the contact 321 is opened, thereby breaking the circuit of the locking magnets 102 of all the keys, thereby permitting the keys which were depressed to be returned to their normal positions. 115

As the sender sequence-switch reaches the 13th position, a contact 322 is closed, completing a circuit from battery 235, through the power magnet 214 of the mechanism which winds up the spring 208 of the point 120 finder apparatus. The magnet 214 when excited attracts the iron plate 212 into engagement with the driving roller 213, whereby said plate 212 is rotated in a direction to wind up the spring 208. As the plate 212 begins to rotate, the cam lever 216 engaged thereby closes contact 215, which maintains the circuit of the power magnet 214 until 125

the plate 212 shall have made one complete revolution, whereupon the end of lever 216 enters the notch in the periphery of said plate 212 and opens said contact 215, causing the power magnet 214 to be deenergized.

As the sender sequence-switch leaves its 13th position, it opens its contact 310 controlling the local locking circuit of the stop relay 219. Said stop relay is thereby released and closes at its back contact 231 a circuit which will be completed for the motor magnet 317 of the sender sequence-switch when the latter arrives at the 14th position, so that said sequence-switch will not stop at the 14th position, but will travel on to the first or normal position. In this position the contact 323 is closed, to maintain the local circuit for stepping magnet 205 through contacts 224 and 233 and interrupter 221.

The finder brush 201 will thus continue to travel around toward its normal position s^1 ; and upon arriving at this position the cam 222 will open the contacts 223 and 224, thus breaking the circuit for the stepping magnet 205, and permitting the finder brush to come to rest in its normal position s^1 .

When the sequence-switch associated with the first selector moves from its 7th to its 8th or talking position, the contact 416 is opened, thereby breaking the circuit for the sender controlling relay 300 (Fig. 2).

The sending apparatus has thus been completely restored to normal position, and is now ready to serve any of the other connecting circuits which the operator may now put into use, the sending apparatus being entirely free from any connection with the telephonic circuit which it has caused to be established between the calling subscriber 401 and the called subscriber 950.

When the line relay 520 of the final selector is released at the end of the final sending operation, a circuit is closed from battery 506, through the motor magnet 507 of the final selector sequence-switch, contact 584 of said sequence-switch, back contact of the line relay, to earth; whereby the sequence-switch is moved to the 5th position.

In this position the busy test of the called line is made. When the test brush 53 of the final selector comes to rest upon the terminal of the called line, a test circuit is completed from the test terminal of said line to the test brush of the selector, and through contact 552 of the sequence-switch, windings 553 and 554 of the polarized test relay 550 and contact 555 of the sequence-switch, to earth. The test relay 550 is marginal in its operation. It is adjusted to attract its armature upon current received from the test terminal of a line that is free, but will not respond to current received from the test terminal of a line that is busy, the test relay 550 in the latter case being shunted by a path

from the test terminal of a busy line to earth at the already-existing connection.

As the final selector sequence-switch reaches the 5th position, a circuit will be completed for the motor magnet, whereby 70 said sequence-switch will be advanced to the 9th or busy-back position, at which it will stop, if the line tested is busy, but if the line tested is free a circuit will be maintained for the motor magnet of the sequence-switch 75 until the 9th or busy-back position has been passed. If the line tested is busy the circuit for the motor magnet will be from battery 506, through said motor magnet 507, contact 541 of the sequence-switch, and back contact 551 of the test relay to earth. The contact 541 is maintained from the 5th to the 8th position, and the local contact 20^c is also closed between the 5th and 9th positions, so that the sequence-switch will in any 85 event reach the 9th position. In this position the free pole of the busy tone interrupter 560 is connected through test contact 542 of the sequence-switch to the trunk conductor 502. The circuit is thus intermittently completed from the battery 450 bridged between the windings of the repeating coil in the cord circuit (Fig. 3) through supervisory relay 415, out over the conductor 502 of the trunk line, to the final selector, 90 through contact 542 of the sequence-switch thereof, and interrupter 560, to earth. The supervisory lamp 413 before the operator will thus be caused to flash, indicating to her 95 that the line for which connection has been 100 asked is busy.

If the line tested is free, the test relay will complete a circuit from battery 506, through motor magnet 507 of the final selector sequence-switch, to a contact 540 thereof, and front contact of the test relay 550, to earth. This circuit is maintained until after the sequence-switch leaves the 9th position, and the local switch contact 510 is closed between the 9th and 11th positions, so that 110 the sequence-switch instead of stopping at the 9th or busy-back position, will run through to the 11th position.

As soon as the sending operation was completed, and the contact 461 closed at the 115 sequence-switch of the first selector, the line relay 520 at the final selector was excited by current from battery 504 flowing through said line relay to trunk conductor 501, back through the first selector and contact 461 120 of its sequence-switch, to the ground connection 452 of the repeating coil in the cord circuit.

The line relay at the final selector being thus excited at the time its sequence-switch 125 reaches the 11th position, a circuit will be completed from battery 506, through the motor magnet 507 of the sequence-switch contact 508 thereof, front contact of the line relay 520, to earth; whereby the sequence- 130

switch will be moved to the 13th position, contact 20^a being closed between the 11th and 13th positions.

In the 13th position the contacts 536 and 537 are closed, connecting the poles of the ringing generator 556 to the line brushes 51 and 52 of the selector, thus applying ringing current to the called line. When the subscriber answers the call by removing his telephone from its hook, the increased current flowing through the supervisory relay 557 associated with the final selector causes said relay to close a circuit from battery 506, through motor magnet 507 of the sequence-switch, contact 543 thereof, front contact of the supervisory relay 557, to earth; whereby the sequence-switch is moved to the 14th or talking position. In this position the contact 561 and 562 are closed, completing the talking circuit for the trunk line, through the repeating coil 570.

In the 14th or talking position of the final selector sequence-switch, the supervisory relay 557 will receive current from the battery 571 bridged between two of the windings of the repeating coil, and will control at its front contact a path to ground from the trunk line conductor 502, thereby controlling the supervisory relay 415 in the cord circuit, which in turn controls the supervisory signal lamp 413 in the usual manner.

Disconnection.—When the operator receives the disconnect signal, indicated in the usual way by the lighting of the supervisory lamps 412 and 413, she takes down the connection by removing the answering plug 403 from the springjack of the calling line. The cord relay 405 is thus released and 40 closes a circuit from battery 408, through the motor magnet 407 of the sequence-switch associated with the first selector, contact 472 thereof, and back contact of cord relay, to earth. The local contact 20^b of the sequence-switch being closed between the 8th and 13th positions thereof, said sequence-switch will be carried through to the 13th position, whereupon a circuit will be completed from battery 408, through motor magnet 407, contact 473, back contact of supervisory relay 415, wire 474, contact 475 of the sequence-switch, to earth. The sequence-switch will thus be carried to the 14th or "return" position in which a circuit will be completed 50 from battery 425, through power magnet 77 of the selector, contact 476, back contact of the line relay 420, to earth. The power disk 73 being off-normal, its surface is nearer to the return driving roller 74 than to roller 60 75, so that said disk will be attracted into engagement with the roller 74, and the brush-carrying frame of the selector will be rotated back to normal position. As the cam 80 in the return movement closes the contact 65 82, a circuit is completed from battery 408,

through motor magnet 407 of the sequence-switch, contact 482, contact 82, spring 81, to earth, whereby the sequence-switch is moved to its 15th position. When the rotary brush carrier of the selector reaches its normal position the cam 80 opens contact 82 and closes contact 83, completing a circuit from battery 408, through motor magnet 407, contact 433 of the sequence-switch, contact 83 closed by the cam, to earth. The sequence-switch of the first selector has sixteen positions, but the local contact 410 is closed between the 15th position and the 1st or normal position, so that the sequence-switch is carried through to its normal position. Upon leaving the 15th position the contact 476 is opened, breaking the circuit for the power magnet, and stopping the rotation of the brush carrier frame. Both the first selector and its sequence-switch are now in normal position.

When the operator removed the plug from the springjack, and the sequence-switch of the first selector left its 8th or talking position, contact 361 was opened, thereby breaking the circuit of the line relay 520 at the final selector, which was excited during the connection. The line relay 520 in recovering establishes a circuit from battery 506, through motor magnet 507 of the sequence-switch associated with the final selector, through contact 584 thereof, and back contact of line relay 520, to earth. The sequence-switch is therefore moved to the 15th position, in which contacts 561 and 562 are open, and contact 576 closed, the latter completing a circuit from battery 525, through the power magnet 77 of the final selector, contact 576 and back contact of the line relay 520, to earth. The brush carrier of the selector is now rotated back to normal position, as previously described with reference to the first selector. When the cam 80 of the final selector in returning closes the contact 82, a circuit is completed from the battery 506, through the motor magnet 507, contact 532 of the sequence-switch, contact 82 and spring 81, to earth. The sequence-switch is thus moved to the 16th position, and as the rotary element of the selector reaches its normal position cam 80 closes contact 83 of the final selector, and a circuit is completed from battery 506, through motor magnet 507, contact 533 of the sequence-switch, contact 83 and spring 81, to earth. The sequence-switch of the final selector has seventeen positions, but as the local contact 510 is closed between the 16th and the 1st positions, the sequence-switch upon leaving the 16th position runs through to the 1st or normal position. All the apparatus of the system is now in the normal condition.

Interference with orderly process of selection.—It may happen that after an operator has answered a call, and at any time before

the connection has been finally established, the answering plug may be withdrawn; or there may be a temporary break in some of the main circuits, from one cause or another. One of the features of this system is that in case the normal orderly progress of establishing a connection is thus interfered with, the apparatus and circuits of the system will not be permanently disorganized, but will be automatically restored to normal under the control of circuits which are purely local.

Each automatic selector co-operates with its sequence-switch or controlling device to govern the local operating circuits of these devices in such a manner that when the rotary element of either device is off normal, due to a partially completed operation, circuits are progressively established for the motor magnets of said devices to return them both to normal, each device at different stages in its movement closing circuits for the motor magnet of the other, until both have returned. In the regular operation of the system this progressive travel of the two devices which would finally result in returning them both to normal, is only checked, so to speak, at certain stages of the operation by controlling apparatus which is dependent upon a flow of current in one of the principal circuits, extending, for example, to a distant point. If such flow of current is permanently interfered with, either accidentally or otherwise, when the selector or sequence-switch is off normal, the progressive operation of the two devices can no longer be checked, and they proceed automatically with the requisite series of operations which results in both being returned to normal condition. A similar provision is made respecting the sending apparatus and its sequence-switch. None of these devices therefore can be permanently stalled in an off normal position, nor can a selecting operation of one of these devices be started from any other than the proper normal position.

It may frequently happen that the operator, after having answered a call, will simply withdraw the answering plug 403 from the springjack of the calling line, without having depressed any of the keys—as where the subscriber has merely asked for information. The first selector and its sequence-switch are under control of the cord relay 405. The back contact of this cord relay is adapted to complete a circuit for the motor magnet 407 of the sequence-switch associated with the first selector, in the third position of said sequence-switch, and also from the 6th to the 12th positions thereof inclusive.

If the operator should withdraw the answering plug immediately after having depressed the listening key, and before having

depressed any of the keys of the sender, the sequence-switch associated with the connecting circuit and selector will be in the 3rd position, and a circuit will therefore be completed through the motor magnet of the sequence-switch, through contact 472 thereof, and back contact of the cord relay 405, to earth. This will advance the sequence-switch to the 4th position, in which the power magnet 77 and trip magnet 67 of the selector will be connected in series in a circuit completed at contact 430 of the sequence-switch. The brush carrier of the selector will therefore begin to rotate and a set of brushes will be tripped. As soon as the shaft 50 of the selector begins to rotate, the cam 80 closes contact 81, 82, and completes a circuit for the motor magnet of the sequence-switch, through contact 432 thereof, whereby the sequence-switch is advanced to the 5th position. In this position a circuit is completed for the line relay 420, through contacts 422 and 433 of the sequence-switch to the test brush 53 of the set which has been tripped, and to ground through the metal plate 70. The relay 420 which is thus excited short-circuits the trip magnet 67. The power magnet 77 remains excited, however, by current through contact 426 and front contact of the line relay, and the rotary element of the selector continues to advance the brushes until they are carried beyond the trip range, whereupon the cam 80 closes contact 81, 83, completing a circuit through contact 433 of the sequence-switch for the motor magnet thereof, whereby said sequence-switch is advanced to the 6th position. In this position a circuit is completed for the motor magnet 407 of the sequence-switch, through contact 472 thereof (closed from the 6th to the 12th positions inclusive) and back contact of the cord relay; whereby the sequence-switch advances to the 13th position. In leaving the 6th position the circuits for the line relay 420 and motor magnet 77 are broken, and the brushes therefore stop at the end of the trip range, while the interrupter roller 85 is on the top of the long tooth 89, and before the brushes have come into contact with the first set of line terminals in their level. In the 13th position contacts 473 and 475 are closed, whereby the sequence-switch is advanced to the 14th position. The power magnet 77 is now again energized by circuit through contact 476 of the sequence-switch, and back contact of the line relay, to return the selector to normal position, the operation from this point on being as described under the heading "Disconnection."

If the cord relay 405 is de-energized by the withdrawal of the plug while the sequence-switch of the first selector is in any position from the 6th to the 12th inclusive, said sequence-switch will be advanced to the

13th position by the circuit for the motor magnet 407, closed at the back contact of said cord relay. In the 13th position the contacts 473 and 475 are closed, whereby the 5 sequence-switch is advanced to the 14th position, in which a circuit is closed for the power magnet 77 of the selector to return the bush-carrier to normal, as previously described, the sequence-switch also being re- 10 turned to normal as described under the heading "Disconnection." When the operations of the sequence-switch and selector reach a stage in which the sequence-switch is in the 13th position, the further operations 15 are self-controlled and independent of the cord relay, so that they cannot in any event be checked after this point, until both devices arrive at normal.

When the operator removes the answering 20 plug without having depressed any of the keys of the sender, and the selector sequence-switch runs through its various positions in returning to normal, the closure of contact 416 therefrom from the 3rd to the 7th positions 25 inclusive completes the circuit for the control relay 300 of the sender. Said control relay 300 therefore completes a circuit for the motor magnet 317 of the sender sequence-switch, whereby the latter is advanced to its second position. The contact 324 of the sender sequence-switch is closed from the 2nd to the 8th positions thereof 30 inclusive, connecting the motor magnet 317 to the back contact of the control relay 300. This relay 300 remains energized until the sequence-switch of the first selector leaves its 7th position, whereupon the relay 300 is released, and closes at its back contact the circuit for the motor magnet of the sender sequence-switch, whereby the latter is advanced to its 9th position; and as the contact 20^a of the sequence-switch is closed between the 8th and 14th positions, the sender sequence-switch continues to advance until 40 it has completed a revolution and returns to normal. In the third position of the sender sequence-switch the contact 309 controlling the selecting circuit is closed, but as the sequence-switch of the sender is not advanced until the sequence-switch of the selector has passed the point at which the battery 421 was connected to the sender lead 424, the stepping relay 218 is not excited. The only result at the sender, therefore, if 45 no keys have been depressed, is that the sequence-switch of the sender makes a complete revolution, and returns to normal.

Considering now the effect if one or more of the sender keys had been depressed before 50 the operator removed the plug; the depression of a hundreds key closes a circuit which will be completed at contact 306 of the sender sequence-switch in the second position thereof. The operation of the sender 55 will therefore take place as previously de-

scribed in tracing a complete connection, until the control relay 300 is deenergized by the opening of contact 416 of the sequence-switch associated with the first selector, which will occur, as we have seen, 70 when the last-mentioned sequence-switch is running through to normal after the plug 403 has been withdrawn. Upon the de-energization of the control relay 300 of the sender at any time from the second to the 75 8th positions inclusive of the sender sequence-switch, a circuit will be completed for the motor magnet 317 of said sequence-switch to carry it to the 9th position; and the local circuit for said motor magnet is 80 then continuously closed at contact 20^a until the normal position is reached, as before described. If the finder brush 201 of the sender has been moved away from its normal position in the course of such an un- 85 completed selection, the contact 223 will be closed by the cam 222 upon the rotary shaft of the point finder. The notch into which the end of contact spring 233 falls in the normal position of the finder brush is 90 deeper than the notches into which the end of said spring falls in the second and third starting positions s^2 , s^3 , so that contact 224 will be opened when the finder brush reaches position s^2 or position s^3 , but contact 95 223 will be opened only when the finder brush is resting in its normal position. Therefore, if the finder brush is off normal when the sender sequence-switch, having made a complete revolution, returns to its 100 first or normal position, a circuit will be completed from battery 225, through the step magnet 205, contact 323 of the sequence-switch, contact 223 operated by cam 222, and through the interrupter 221, to earth, and 105 the finder brush will be carried around to normal.

When the finder brush has reached its normal position, the contact 223 is opened, breaking the local interrupter circuit for the 110 magnet 205 and causing the finder brush to come to rest.

Whenever the point finder has been displaced from its normal position, and the sender sequence-switch is running through its 115 13th and 14th positions closes contact 322, a circuit is completed for the power magnet 214 of the winding apparatus, whereby the power plate 212 is rotated to wind up the spring 208, until said power 120 plate reaches its normal position in which contact 215 is opened.

Turning now to the final selector (Fig. 4); if the sequence-switch and selector have been displaced from normal, the progressive 125 operations which would result in returning both of these devices to normal can be checked only by the line relay 520, in response to current flowing over the main circuit conductor 501. If the line relay is 130

permanently deprived of current at any stage of the operation, a circuit will be completed for either the motor magnet of the sequence-switch or the power magnet of the selector, and the device which is thus set in motion will in its operation bring the other device into action, and the local operating circuits thus successively established will cause both devices to be restored to normal.

5 If the line relay 520 is deenergized when the sequence-switch is in the 2nd position (to take the most extreme case) a circuit will be completed for the power magnet 77, through contact 576 of the sequence-switch and back contact of the line relay 520, whereby the brush-carrier of the selector will be started in rotation. The cam 80 thereupon closes contact 81, 82, completing a circuit for the motor magnet 507 of the 10 sequence-switch associated with the final selector, through contact 532 of said sequence-switch, whereby the latter is advanced to its third position. In this position contact 530 is closed, whereby the trip 15 magnet 67 is excited in series with the power magnet, the brush-carrier begins to rotate, and a set of brushes is tripped. The line relay 520 is thereupon excited by current in the local circuit, through contact 538 20 of the sequence-switch to the test brush 53 of the selector and grounded plate 70, and said relay closes at its front contact a short circuit of the trip magnet 67. When the remaining brushes have passed the trip 25 range, the cam 80 closes contact 81, 83, completing a circuit for the motor magnet of the sequence-switch, through contact 533 thereof, whereby the sequence-switch is advanced to the 4th position. As the sequence- 30 switch leaves the 3rd position the contact 538 is broken, disconnecting the line relay from the test brush. The interrupter roller 85 is now rising over the long tooth 89, and a circuit still exists for the line relay 520, 35 through contact 522, back contact 528 of the trip magnet, contact 86, 87, to earth. When the interrupter roller 85 rides off the long tooth 89 into the following notch, the circuit for the line relay 520 is broken, and the 40 line relay releases its armature, closing at its back contact a circuit through contact 584 to the motor magnet of the sequence-switch, whereby the latter is advanced from the 4th to the 5th position. From the 5th 45 to the 8th positions inclusive a circuit is completed for the motor magnet 507, through the contact 541 of the sequence-switch, and back contact 551 of the test relay, to earth. As the local contact 20 does not open between the 9th and 11th positions, the sequence-switch therefore runs through to the 11th position. When the sequence-switch leaves the 4th position, the circuit 50 for the power magnet 77 is opened, and the brush-carrier comes to rest in the position 55

in which the interrupter roller 85 is resting in the first notch beyond the long tooth 89, the brushes not having yet reached the first row of line terminals.

When the sequence-switch reaches the 11th position a circuit is completed for the power magnet 77, through the contact 576 of the sequence-switch, and back contact of the line relay 520. The brush carrier of the selector therefore is started to rotate 75 back toward its normal position. When in this return movement the cam 80 closes the contact 81, 82, a circuit is completed for the motor magnet 507 of the sequence-switch, through the contact 532 thereof, so whereby the sequence-switch is moved to the 16th position, the contact 532 being closed from the 11th to the 15th positions inclusive. When the brush-carrier has reached normal, the cam 80 allows the contact 81, 83, to be 85 closed, completing a circuit for the motor magnet 507 of the sequence-switch, through contact 533 thereof, so that the sequence-switch in turn is advanced from the 16th to the 1st or normal position. 90

I claim:—

1. The combination with a selector having a movable switch-member, a magnet 420 and means controlled by said magnet for causing the movement of said switch-member, of a point-finder, a stepping relay and means controlled by successive excitations thereof for advancing said point-finder, a circuit including said magnet 420 and said stepping relay, means operated 95 by the selector for applying impulses of current in said circuit, a set of keys associated with the finder, and means brought into action by the finder under control of an actuated key for opening said circuit; 100 whereby the selector and point-finder are operated in unison to an extent predetermined by the actuated key. 105

2. In a telephone exchange system, the combination with selector mechanism, of 110 sender apparatus comprising a rotating controller member having its total arc of travel arranged in successive divisions, means for operating a selector in unison with said controller member during the travel of the 115 latter through a predetermined fraction of each division, and automatic means for advancing said controller member independently through the remainder of each division. 120

3. In a telephone exchange system, the combination with automatic selectors, of 12 sender apparatus comprising a finder brush, a series of contact terminals adapted to be traversed by said brush in sequence, said 12 terminals being arranged in a plurality of divisions, electromagnetic stepping mechanism for advancing said finder brush, means for operating a selector in unison with said stepping mechanism during the 130

advance of the finder brush over a part of the terminals in each division, and means for operating said stepping mechanism independently to advance the finder brush over the remaining terminals in each division.

4. The combination with selector mechanism, of a sender apparatus comprising a finder brush, a series of terminals arranged to be traversed by said brush, said terminals being arranged in a plurality of divisions, keys corresponding to said terminals, electromagnetic stepping mechanism adapted to advance said finder brush over said terminals, a selecting circuit and means controlled by current therein for operating a selector in unison with said stepping mechanism during the travel of said finder brush to a predetermined point in each division, 15 a stop-relay adapted to open said selecting circuit, means controlled by each key for selecting such point by establishing a circuit for said stop-relay to be completed by the finder brush in its contact with the terminal 20 corresponding to such key, and means controlled by the stop-relay for advancing said finder brush from such selected terminal in each division to the beginning of the next division.
5. A sending apparatus having a series 25 of contacts and a finder brush for traversing the same, a rotary switch element for moving said brush, electrically controlled spring-driven clockwork mechanism adapted to rotate said switch element, a source 30 of mechanical power adapted to wind the spring of said clockwork mechanism, and means, brought into action by said switch element in completing a predetermined operation, for applying such power to wind the spring.

6. A sending apparatus comprising a rotary controlling element, driving gear therefor, an escapement for said driving gear, a 45 step magnet, a local circuit for said step magnet, a relay adapted to respond to selecting impulses, controlling said local circuit containing the step magnet, and switching means actuated in response to a predetermined operation of said controlling element, adapted to break said local circuit.

7. A sending apparatus comprising a 50 finder, a series of terminals adapted to be traversed by said finder, mechanism for moving said finder, an escapement for said mechanism, a step-magnet arranged to operate said escapement, a circuit for said step magnet, means for applying electrical impulses in said circuit to cause the finder to 55 be stepped along by the action of said escapement, a relay controlling the circuit of said step magnet, a series of keys corresponding to said terminals, and means controlled by any key for establishing a circuit 60 for said relay to be completed by the finder

engaging the corresponding terminal; whereby the extent of operation of the finder is determined by the particular key actuated.

8. The combination with an automatic sending apparatus, of an automatic sequence-switch adapted to establish a series of local operating circuits therefor, and means brought into operation by each of said devices when displaced for returning the other device to normal position.

9. A sending apparatus comprising a point-finder, keys adapted to control the operation of said point-finder, a sequence-switch adapted to establish successive circuits for the operation of said point-finder, means controlled by a key for starting said sequence-switch in operation, and means brought into action by successive operations of said point-finder for advancing said sequence-switch.

10. In a telephone exchange system, the combination with selecting mechanism, a sending circuit therefor and a controlling switch in said circuit, of a rotary point 90 finder, means for advancing said point finder through different divisions or arcs of its total range of movement, means controlled by the point finder in reaching a point in each division predetermined by the 95 corresponding key for operating said controlling switch, and means for advancing said point finder independently through the remainder of each division.

11. In a telephone exchange system, the combination with a selector, of sending apparatus therefor comprising a finder brush, a series of contacts, controlling switches one for each contact, means for advancing said 100 finder brush in unison with said selector to 105 a contact corresponding to an operated controlling switch, and means for continuing the advance of said finder brush.

12. In a telephone exchange system, the combination with selecting mechanism, a sending circuit therefor and a controlling switch in said circuit, of a point finder, means for advancing said point finder in unison with said selecting mechanism to a point corresponding to the selection desired, 110 and means for continuing the advance of said point finder beyond said point independently of the selecting mechanism.

13. In a telephone exchange system, the combination with a selector, of a point 115 finder for controlling the movement thereof, a series of contacts, controlling switches one for each of said contacts, means for advancing said point finder over said contacts in succession and in unison with said selector to a point corresponding to an operated key, and means local to the point finder for continuing the advance of said point finder beyond said contact.

14. In a telephone exchange system, the

combination with sending apparatus comprising a point finder the total range of travel of which is arranged in divisions, of a set of keys associated with said sender apparatus adapted to establish operative points in the divisions of the range of travel of said point finder, a selector, means for advancing said point finder in unison with said selector to a point in a division, a stop relay, a circuit therefor completed when said point finder reaches said point, and means controlled by said relay for advancing said point finder through the remainder of said division.

15. In a telephone exchange system, the combination with sender apparatus comprising a point finder having its total range of travel arranged in divisions, selector mechanism, and means for advancing said point-finder in unison with said selector mechanism to a predetermined position in a division, a local circuit for controlling the advance of said point finder through the remainder of the division, and a relay brought into operation when said point finder reaches said predetermined position for transferring the control thereof to said local circuit.

16. In a telephone exchange system, the combination with a telephone line extending from a substation to a central office, of a connecting-circuit at the central office, a connection-switch for uniting said connecting-circuit with said line, mechanical switching mechanism for uniting said connecting-circuit with other telephone lines, a keyboard for the operator comprising keys representing the digits of the telephone lines of the exchange, and automatic means controlled by the key or keys representing any desired line when depressed for operating said switching mechanism to unite said connecting-circuit with said telephone line.

17. In a telephone exchange system, the combination with a telephone line extending from a substation to a central office, of a connecting-circuit at the central office, a connection-switch for uniting said connecting-circuit with said telephone line, mechanical switching mechanism adapted when operated to unite said connecting-circuit with another line in the exchange, a keyboard for the operator comprising keys representing the digits of the lines in the exchange, and automatic mechanism controlled by each digit key representing a line for operating said switching mechanism, the mechanism of each digit key being successively operated until the switching mechanism connects with the desired line.

18. The combination with a line switching device comprising an arm arranged to have two movements differing in character, of controlling apparatus comprising digit keys and mechanism controlled thereby

adapted when said keys are operated to advance said arm through both movements.

19. In a telephone exchange system, the combination with a telephone line extending from a substation to a central office spring-jack, of a plug and plug circuit at the central office, mechanical switching mechanism, keys representing telephone lines in the exchange, and mechanism actuated by a key or keys representing a desired line for operating said switching mechanism to connect the plug circuit with said line.

20. In a semi-automatic telephone exchange system, the combination with a connecting circuit adapted to be united with a calling line, of selector mechanism adapted to extend said connecting circuit to other lines, automatic sender apparatus arranged to control said selector mechanism, and a set of numeral keys adapted to be actuated in combination to represent any line number, said sender apparatus being adapted under the control of such combination of keys to cause sequential operations of the selector mechanism to extend the circuit to the line designated by such combination of keys.

21. The combination with telephone lines and a central station to which they extend, of mechanical switching apparatus for connecting the lines, said apparatus having a plurality of movements to effect different selective operations, and apparatus at the central station provided with sets of digit keys, each set controlling one of the selective operations, substantially as set forth.

22. In a telephone exchange system, the combination with subscribers' lines, of an operator's connecting circuit having means at one end for uniting it with a calling line, automatic line-switching mechanism adapted selectively to extend such circuit to any other line, and an operator's sending apparatus comprising a bank of numerical keys, automatic controller mechanism adapted to cause selecting operations of said line-switching mechanism, and automatic sequence-switching mechanism adapted to cause a series of selector-controlling operations to occur in definite order under control of different keys.

23. In a telephone exchange system, the combination with a telephone line extending from a substation to a central office, of a connecting-circuit at the central office, a connection-switch for uniting said connecting-circuit with said telephone line, mechanical switching mechanism adapted when operated to unite said connecting-circuit with another line in the exchange, a keyboard for the operator comprising keys representing the digits of the lines in the exchange, and automatic mechanism controlled by the keys representing the digits of a line for operating said switching mechanism, the mechanism controlled by said

digit keys being successively operated until the switching mechanism connects with the desired line.

24. A sending apparatus having a point 5 finder, keys, and an automatic sequence switch adapted to bring said point finder successively under control of different keys.

25. In a semi automatic telephone exchange system, the combination with subscribers' lines, operators' answering equipment, switches for connecting calling lines with said answering equipment, and selectors adapted to extend the circuits of calling lines to other lines, of a keyboard associated with said answering equipment and adapted to be manipulated by the operator to register the number of lines wanted and a controller operating in conjunction with said keyboard to govern said selectors.

26. The combination with a plurality of selector mechanisms, of a plurality of sets of numerical keys, a point finder, means for moving said point finder successively under control of keys of different sets and means 25 for bringing said selector mechanisms successively under control of said point finder.

27. The combination with mechanical line switching mechanism, of sending apparatus adapted to be set to indicate the number of 30 the desired line and to operate said mechanism to connect with said line, means for locking said sending apparatus in its operative position, and means automatically operating when said mechanism unites with a 35 desired line for restoring said apparatus.

28. The combination with a plurality of keys, of an automatic controlling apparatus adapted to be selectively controlled by said keys when depressed, means for locking 40 each key in its depressed position, and means actuated automatically by said controlling apparatus in completing its operation for releasing the depressed keys.

29. The combination with a plurality of 45 keys, of an automatic controlling apparatus adapted to be selectively controlled by said keys when depressed, a magnet controlling the release of the depressed keys, a circuit for said magnet, and a switch automatically 50 operated by said controlling apparatus in completing its operation governing said circuit.

30. The combination with mechanical line switching mechanism, of keys having plungers 55 representing the digits of telephone lines, means automatically operated upon the depression of the plungers of said keys representing the digits of the desired line, for operating said mechanism to connect 60 with said line, means for locking said plungers in their depressed positions, and electromagnetic mechanism actuated when the mechanism unites with the desired line for restoring said plungers.

31. A sender apparatus comprising an

automatic controlling device, a set of keys, means controlled by the actuation of any key for setting said controlling device in operation, and automatic means for operating said device successively under the control of 70 different keys.

32. In an automatic telephone exchange system, the combination with a selector, of a sending apparatus comprising a finder brush, a series of terminals in the path of 75 said finder brush, a series of keys adapted when depressed to change the electrical condition of corresponding terminals in the series, electromagnetic stepping mechanism for causing the movement of said finder 80 brush over said terminals, means controlled by any key of the series for establishing a controlling circuit between said selector and said stepping mechanism, means for applying pulsating current in said circuit, and for 85 advancing the selector and stepping mechanism in unison with such pulsations, and means controlled by the engagement of the finder brush and the terminal corresponding to a depressed key for interrupting said 90 controlling circuit.

33. In an automatic telephone exchange system, the combination with a selector, of a sending apparatus having a finder brush, a series of terminals adapted to be traversed 95 by said brush, electromagnetic mechanism for advancing said finder brush over said terminals, a controlling circuit extending between said electromagnetic mechanism and said selector, means controlled by current 100 in said circuit for advancing said finder brush in unison with said selector, means for establishing a circuit under the control of said finder brush and one of the terminals in its path, and a stop-relay in said 105 last mentioned circuit adapted to open said first-mentioned controlling circuit.

34. The combination with selector mechanism, of a sender apparatus comprising a 110 finder brush, a series of terminals arranged to be traversed by said brush, said terminals being arranged in a plurality of divisions, keys corresponding to said terminals, electromagnetic stepping mechanism adapted to advance said finder brush over said 115 terminals, a selecting circuit and means controlled by current therein for operating said stepping mechanism in unison with a selector during the travel of said finder brush to a predetermined point in each division, a stop-relay adapted to open said selecting 120 circuit, means controlled by each key for selecting such point by establishing a circuit for said stop-relay to be completed by the finder brush in its contact with the terminal corresponding to such key, and means controlled by the stop-relay for advancing said finder brush from such selected terminal in each division to the beginning of the 125 next division.

35. The combination with a selector of an automatic sending apparatus, means for establishing a controlling circuit between the sending apparatus and the selector, means controlled by flow of current in such circuit for operating such selector and sending apparatus in unison, a set of keys controlling said sending apparatus and a switch operated by the sending apparatus to open said 10 controlling circuit after an operation of said sending apparatus predetermined by said set of keys.
36. The combination with mechanical line switching mechanism, of digit keys representing the digits of telephone line numbers, means automatically actuated by the operation of the keys representing any line for operating the mechanism to connect with said line, means for locking said keys 20 in their operated positions, and means automatically operated when said mechanism connects with the desired line, for restoring said keys.
37. In a telephone exchange system, the combination with a telephone line extending from a substation to a central office, of a connecting circuit at the central office, a connection-switch for uniting said connecting circuit with the line, mechanical switching mechanism for said connecting circuit, keys having plungers representing the digits of lines in the exchange, means automatically operated upon the depression by the operator of plungers representing a desired line, 35 for operating said switching mechanism to unite the connecting circuit with such line, means for locking said plungers in their depressed positions, and means, automatically operated when said mechanism connects with the desired line, for restoring said plungers.
38. In a controlling apparatus for telephone line selectors, a plurality of registering means, and a transmitting mechanism having a movable member the travel of which is successively governed by the registering means.
39. In a telephone exchange system, the combination with an operator's cord-circuit having an answering plug at one end and a selector at the other end, of a subscriber's line having an answering springjack, a local circuit completed by the answering plug and springjack, a relay in said circuit, an automatic sequence-switch adapted to establish local operating circuits for said selector, said sequence-switch having a motor magnet for operating the same, and a circuit for said motor magnet controlled by said relay.
40. The combination with telephone lines having springjacks, of an operator's connecting circuit having an answering plug at one end and an automatic selector at the other end, an automatic sequence-switch 65 adapted to establish local operating circuits for said selector, said sequence-switch having a motor magnet for operating the same, and a local circuit for the motor magnet of the sequence-switch controlled at back and front contacts of said relay.
41. In a telephone exchange system, the combination with an operator's connecting circuit, having a selector associated therewith, of a sequence-switch associated with said connecting circuit, said sequence-switch having a motor magnet for operating the same, and being adapted to establish local operating circuits for said selector, means for initially exciting said motor magnet, a sending apparatus, a circuit established by the initial operation of said sequence-switch to bring its motor magnet under control of 85 said sending apparatus, and circuits for operating the selector established by said sequence switch under control of said sending apparatus.
42. In a telephone exchange system, the combination with a selector, of an automatic sending apparatus adapted to control the operation of said selector, a sequence-switch controlling local operating circuits for said selector, a sequence-switch controlling local 95 operating circuits for said sending apparatus, a circuit for operating the sender-sequence-switch closed by the sequence-switch of the selector, and a circuit for operating the sequence-switch of the selector, controlled by the sequence-switch of the sender.
43. The combination with an operator's connecting circuit, of a selector and an auxiliary-sequence-switch associated therewith, a sender, a sequence-switch associated with 105 said sender, a controlling circuit adapted to be established between the sender and selector by said sequence-switches acting jointly, means at the connecting circuit for initially operating its associated sequence-switch, a circuit 418 for the sender sequence-switch controlled by the selector sequence-switch, and a circuit 419 for the selector sequence-switch controlled by the sender sequence-switch.
44. A selector having a movable switch member, a magnet 420 and means controlled by said magnet for moving said switch member in combination with a sending apparatus having a traveling controller-member, a magnet and means controlled by said magnet for advancing said controller member, a circuit adapted to include the magnets of said selector and said sending apparatus, an auxiliary automatic switch adapted to close said circuit at the sender end thereof, and an auxiliary switch at the selector responsive to said switch at the sender, for completing the circuit at the selector end.

45. In a telephone exchange system, the combination with an operator's connecting circuit, of a selector associated therewith, a sending apparatus, controlling magnets associated with the selector and sending apparatus respectively, a sequence-switch associated with the connecting circuit, a sequence-switch associated with the sending apparatus, circuits whereby said sequence-switches exercise a reciprocal control over each other, and a selecting circuit adapted to include the operating magnets of the sending apparatus and selector, said selecting circuit being controlled by said sequence-switches at the respective ends thereof.

46. In a telephone exchange system, the combination with a plurality of operator's connecting circuits, each having a selector and a sequence-switch associated therewith, of a sender, a sequence-switch associated with the sender, means operated in the use of any connecting circuit for starting its sequence-switch, a circuit for the sender sequence-switch adapted to be completed by such operation of any of the sequence-switches of the connecting circuits, a set of keys associated with the sender, a contact, operated by the sender sequence-switch in response to the depression of one of said sender keys, for completing a circuit to operate the sequence-switch associated with the connecting circuit, and a controlling circuit between the sender and the selector completed by the last-mentioned sequence-switch when it operates in response to the sender sequence-switch.

47. In a telephone exchange system, the combination with a plurality of operator's connecting circuits, each terminating in a selector, of a sending apparatus, lead wires from said sending apparatus extending in multiple to all the connecting circuits, a local controlling switch associated with each selector adapted to switch the same from its corresponding connecting circuit to said lead-wires of the sending apparatus, whereby the operation of said selector may be controlled by said sending apparatus, each local controlling switch having a motor magnet adapted to operate it, a control-wire extending from the sending apparatus to the motor magnets of the controlling switches of all the selectors, each controlling switch being arranged when operated to close a contact connecting its motor magnet to said control-wire, and a switch associated with the sending apparatus for completing the circuit of said control-wire.

48. The combination with a selector having motor mechanism, a controlling magnet and means operated by said magnet when excited for operating said motor mechanism, of a sender, a controlling circuit arranged to be established between the sender and said controlling magnet, means operated by

the motor mechanism of the selector for transmitting impulses over said controlling circuit to the sender, automatic sequence-switches for the sender, and selector, respectively, means for causing the sequence-switch at the sender to close said controlling circuit at the sender end thereof, means whereby said sender sequence-switch also causes the sequence-switch at the selector to complete said controlling circuit at the selector end thereof, whereby said controlling magnet is excited and the motor magnet at the selector started in operation, and switching means actuated upon a predetermined operation of the sender for opening said controlling circuit.

49. The combination with a plurality of operator's connecting circuits, each terminating in a selector, of a sequence-switch for each selector, a sender, a sequence-switch for the sender, a switch associated with each connecting circuit and means controlled thereby for advancing the sequence-switch of the associated selector, a circuit closed by said selector sequence switch, for advancing the sender sequence-switch, call-registering means for the sender made operative by such advance of the sequence-switch thereof, a circuit for further advancing the sender sequence-switch closed upon the actuation of said call-registering means, a circuit for further advancing the sequence-switch of the selector in response to the last-mentioned advance of the sender sequence-switch, and means made operative by the selector sequence-switch in such further advance for setting the selector in operation under control of the sending apparatus.

50. The combination with telephone lines, of an operator's connecting circuit, a connection-switch adapted to unite said circuit with a calling line, an automatic switch having a source of mechanical power, a clutch magnet controlling the application of power to drive said automatic switch, and means operated in opening said connection-switch for establishing a circuit for said clutch magnet to return said automatic switch to normal position.

51. In a telephone exchange system, the combination with an operator's connecting circuit, of a selector at one end thereof and a switch at the other end thereof for making connection with a calling line, an automatic sequence switch associated with said selector adapted to control the operation of said selector and means operated in making connection with a calling line for controlling the operation of said sequence switch.

52. In a telephone exchange system, the combination with an operator's connecting circuit terminating in a selector, switching mechanism associated with said selector, sender apparatus, switching mechanism associated therewith, a controlling circuit es-

5 tablished by one switching mechanism adapted to govern the operation of the other switching mechanism, and call-registering means associated with said sender apparatus for governing the operation of both switching mechanisms.

10 53. In a telephone exchange system, the combination with a connecting circuit terminating in a selector, switching mechanism associated with said selector for controlling the operation thereof, sender apparatus, switching mechanism associated with said sender apparatus for controlling the operation thereof, means associated with said connecting circuit for initially operating said switching mechanism associated with said selector, a controlling circuit established by said switching mechanism for initially operating the switching mechanism associated with said sender, registering apparatus associated with said sender for continuing the operation of said switching mechanism associated with said sender, and a controlling circuit established by said switching mechanism for continuing the operation of the switching mechanism associated with said selector.

15 54. In a telephone exchange system, the combination with a connecting circuit terminating in a selector, of switching mechanism associated therewith for controlling the operation thereof, sender apparatus, switching mechanism associated therewith for controlling the operation thereof, means associated with said connecting circuit for initially operating the switching mechanism associated with said selector, a controlling circuit established by said switching mechanism for initially starting the switching mechanism associated with said sender apparatus and a controlling circuit established by said switching mechanism associated with the sender apparatus for further continuing the operation of the switching mechanism associated with said selector.

20 55. The combination with mechanical line switching mechanism, of digit keys representing the digits of telephone line numbers, means automatically actuated by the operation of the keys representing any line for operating the mechanism to connect with said line, means for locking said keys in their operated positions, and means automatically operated when said mechanism connects with the desired line for restoring said keys.

25 56. The combination with mechanical switching mechanism, of keys having plungers representing the digits of the numbers of telephone lines, means automatically operated upon the depression of the plunger representing the digit of a line for operating said mechanism, a device for maintaining said plunger depressed, a magnet, and a circuit therefor completed when said

mechanism connects with the desired line to cause said device to release said plunger.

30 57. The combination with mechanical line switching mechanism, of keys having plungers representing the digits of telephone lines, means automatically operated upon the depression of the plunger of said keys representing the digits of the desired line, for operating said mechanism to connect with said line, means for locking said plungers in their depressed positions, and electro-magnetic mechanism actuated when the mechanism unites with the desired line for restoring said plungers.

35 58. In a telephone exchange system, the combination with a telephone line extending from a substation to a central office, of a connecting circuit at the central office, a connection switch for uniting said connecting circuit with the line, mechanical switching mechanism for said connecting circuit, keys having plungers representing the digits of lines in the exchange, means automatically operated upon the depression by the operator of plungers representing a desired line, for operating said switching mechanism to unite the connecting circuit with such line, means for locking said plungers in their depressed positions, and means, automatically operated when said mechanism connects with the desired line, for restoring said plungers.

40 59. The combination with an automatic rotary line switching device, of a controller comprising a keyboard provided with a series of digit plungers, and means controlled by a digit plunger when depressed for operating said device to connect with a terminal thereon which said digit plunger represents.

45 60. The combination with an automatic line switching device, of a controller comprising a keyboard provided with a series of digit plungers, means controlled by a digit plunger when depressed, for operating said device to connect with a terminal thereon which said digit plunger represents, a device associated with said plunger adapted when the same is depressed to engage said plunger to maintain it depressed, a magnet adapted to cause said device to release said plunger, and a circuit for said magnet completed after the operation of the switching device.

50 61. The combination with an automatic selector mechanism, of a source of current, an automatic controller mechanism governing the application of current to operate said selector mechanism, said controller mechanism having a traveling contact device and a series of contact terminals in the path of said contact device, a set of keys, each key being adapted to select a corresponding contact terminal of said controller mechanism, a circuit adapted to be com-

pleted by the traveling contact device and the selected contact terminal, an electro-magnet in said circuit, and means operated by said magnet for stopping the operation 5 of said selector mechanism, whereby the selecting operation is determined according to that one of the keys which is actuated.

62. The combination with mechanical switching mechanisms, of a set of keys, 10 means for operating said switching mechanism under control of said keys, means for locking said keys in their actuated positions, and electro-magnetic mechanism actuated automatically at the end of the operation of 15 said mechanical switching mechanism for restoring an actuated key.

63. In a switching system for central stations, mechanical switching apparatus provided with line terminals, apparatus which 20 may be set by an operator for controlling the movement of said mechanical switching apparatus to cause the selection of the terminals, means for temporarily retaining the setting of the controlling apparatus, and 25 means acting after the completion of the controlling operation for releasing the setting.

64. In a telephone exchange system, the combination with a selector and an operator's connecting circuit, of a sender apparatus 30 adapted to control said selector, and automatic means actuated in the use of said

connecting circuit adapted to bring said sender apparatus into operative relation to said selector.

35

65. In a telephone system, an exchange, subscribers' lines terminating thereat, a link circuit at said exchange, means for connecting said circuit to said lines, automatic switching mechanism for extending a connection to a wanted subscriber's line, a 40 sender for controlling the movement of said switching mechanism, and means automatically actuated incident to the use of said link circuit for associating said sender with 45 said switching mechanism.

66. In a telephone exchange system, subscribers' lines, an operator's connecting circuit, a connection switch associated with 50 said circuit for extending a calling line, a mechanical switch for completing a connection to a wanted subscriber's line, a sender for governing the movement of said switch, and automatic means actuated incident to the use of said connection switch for joining the sender to said circuit.

In witness whereof, I hereunto subscribe my name this second day of September, 55 A. D., 1908.

FRANK R. McBERTY.
